UNITED STATES PATENT OFFICE

WILLIAM S. GUBELMANN, OF BUFFALO, NEW YORK

PRINTING MECHANISM

Original application filed January 10, 1900, Serial No. 1,004. Divided and this application filed October 5, 1916. Serial No. 123,842.

This invention relates to a printing machine, and its principal object is to provide a simple and effective mechanism for this class of machine.

5 A more specific object is the provision of novel mechanism whereby the taking of printing impressions may be effectively controlled.

Another object is to provide simple and efficient means for controlling the positioning 10 of the type for printing desired data.

Other objects will be apparent from the ensuing description and claims.

This application is a division of my application No. 1,004, filed January 10, 1900, and 15 eventuating in Patent No. 1,429,201, dated September 12, 1922.

In the accompanying drawings consisting of ten sheets:

20 Fig. 1 is a fragmentary top plan view of my improved recording machine, parts being omitted.

Fig. 2 is a vertical longitudinal section of the same, taken substantially in line A—A, 25 Fig. 1, and showing the recording mechanism of one column or set of keys in the normal or inactive position.

Fig. 3 is a fragmentary sectional elevation 30 of the printing mechanism of one of the rows of keys viewed from the side opposite to that shown in Fig. 2.

Fig. 4 is a fragmentary sectional elevation taken in line B—B, Fig. 1, and showing the devices whereby numbers are printed in duplicate.

35 Fig. 5 is a horizontal section in line C—C, Fig. 3.

Fig. 6 is a vertical section in line D—D, Fig. 3.

40 Fig. 7 is a view similar to Fig. 2 with the paper carrying device omitted and showing the parts of the recording mechanism in a shifted or active position.

Fig. 8 is a fragmentary longitudinal sectional elevation taken substantially in line 45 E—E Fig. 1, and showing the mechanism whereby words are printed.

Fig. 9 is a longitudinal sectional elevation, 50 taken substantially in line K—K, Fig. 1, and showing particularly the paper carriage and

mechanism whereby different parts of the machine may be thrown into and out of action.

Fig. 10 is a vertical transverse section, on a reduced scale, taken in line L—L, Fig. 9, and 55 showing the means for supporting two rolls of web-paper, for manifold recording.

Fig. 11 is a fragmentary vertical section, taken in line M—M, Fig. 10, and showing means for holding the paper spindle in place. 60

Fig. 12 is a detached side elevation of the paper carriage, viewed from the side opposite to that shown in Fig. 9.

Fig. 13 is a fragmentary detail elevation, 65 illustrating two of the indicator dials and their controlling mechanism.

Fig. 14 is a vertical section, taken substantially in line P—P, Fig. 2.

Fig. 15 is a fragmentary transverse section taken in line Q—Q, Fig. 2, and showing 70 the means for adjusting the paper carriage lengthwise of the line of printing.

Fig. 16 is a vertical transverse section taken in line R—R, Fig. 2.

Fig. 17 is a fragmentary section taken on 75 line S—S, Fig. 7, and showing the preferred means for producing horizontal or cross ruling on the surface which receives the record.

Fig. 18 is a fragmentary cross section showing the means for connecting one of the 80 main printing segments with its companion duplicate printing segment.

Fig. 19 is a fragmentary horizontal section taken in line T—T, Fig. 16, and showing the means whereby the duplicate printing segments 85 may be rendered operative or inoperative.

Fig. 20 is a fragmentary transverse sectional elevation taken in line U—U, Fig. 2, and showing the mechanism for holding the 90 keys in their depressed position and for releasing the same.

Fig. 21 is a fragmentary perspective view of the key holding and releasing mechanism. 95

Fig. 22 is a fragmentary transverse sectional elevation, taken in line V—V, Fig. 2.

Fig. 23 is a view similar to Fig. 22 showing a key in a depressed position.

Fig. 24 is a fragmentary vertical section 100 in line W—W, Fig. 20.

Fig. 25 is a fragmentary longitudinal sectional elevation taken substantially on line F—F, Fig. 1, showing the controlling mechanism for one of the said auxiliary printing mechanisms.

Fig. 26 is a fragmentary longitudinal sectional elevation taken substantially in line G—G, Fig. 1, and showing the mechanism whereby the months and days are recorded.

Fig. 27 is a section taken in line H—H, Fig. 1 and showing the mechanism whereby the year is printed.

Fig. 28 is a section taken in line I—I, Fig. 1 and showing the preferred means for producing vertical ruling on the said sheet which receives the record.

Fig. 29 is a fragmentary sectional side elevation of one of the printing segments showing the means for mounting the type movably thereon.

Fig. 30 is a cross section of the type-segment taken in line BB—BB, Fig. 29.

Fig. 31 is a side view of one of the type carriers viewed from the side opposite to that shown in Fig. 29.

Fig. 32 is a vertical section in line CC—CC in Fig. 7.

Fig. 33 is a fragmentary perspective view showing the key-lever, the main gear segment, the controller arm and printing segment of one of the higher columns of numbers.

Fig. 34 is a fragmentary perspective view of the controller arm and gear segment of the units column of numbers.

Fig. 35, is a perspective view of one of the keys.

Fig. 36 is a fragmentary view, on an enlarged scale, of the mechanism for automatically reversing the ink ribbon of the recording mechanism when the same reaches the end of its movement in either direction.

Fig. 37 is a perspective view showing a modification of the means for producing cross ruling.

Figs. 38 and 39 are perspective views showing different means for producing vertical ruling.

Fig. 40 is a fragmentary perspective view showing a modification in the construction of the dial for indicating each number which is to be recorded.

Fig. 41 is a fragmentary perspective view of the hammer operating mechanism.

While the invention as disclosed in the parent application is embodied in a machine for adding numbers, the principles and construction may be usefully employed in machines for various other purposes. Therefore, in the accompanying drawings and description, the adding mechanism is omitted.

Like letters of reference refer to like parts in the several figures.

General construction

1 represents the main frame of the machine which may be of any suitable construction so as to support the working parts of the machine.

5 (Fig. 2) represents the main gear segments, which in the parent application are utilized to operate suitable accumulating mechanism and which in the present instance are used to move type carriers to position their various types. Each of these gear segments is provided at its lower end with a rearwardly projecting arm 6 which is pivoted loosely on a transverse supporting rod 7. This rod is mounted with its ends on the upper ends of two rock arms 8 which turn loosely with their lower ends on a transverse rock-shaft 9. The rock-arms 8 are connected by a transverse bar 10 which compels the two arms to move back and forth together. In the normal position of the gear segments when the machine is at rest these segments are retracted rearwardly and are elevated.

The gear segments are yieldingly held backwardly by means of springs 11 (Fig. 9) connecting the rock-arms 8 with a stationary part of the frame. Fig. 9 shows one of the springs 11 connecting one of the rock-arms 8 with a transverse stationary bar 12 in the rear part of the machine. The gear segments are moved forward by means of a shifting rock-arm 13, which is preferably secured to the right hand rock-arm 8 and projects rearwardly. Upon raising the shifting rock-arm 13, the rock-arms 8 and gear segments 5 are swung forwardly while upon swinging the shifting rock-arms downwardly, the rock-arms 8 and gear segments 5 are swung rearwardly.

14 (Fig. 2) represents a cam whereby the gear segments are moved forward. This cam is mounted on the upper portion of a vertically swinging rocking frame 15 which is arranged on the right hand side of the machine. This cam is provided at its front end with an incline or cam face 16 and at its rear end with a concentric face 17. When the cam is in its rearmost or retracted position, its incline stands in rear of a roller or projection 18 on the rear end of the shifting arm 13, as shown in Figures 2, 7, and 14. Upon swinging the rocking frame 15, so that the cam 14 moves forwardly, the incline of the latter engages underneath the roller 18 and raises the arm 13, thereby moving the arms 8 forwardly. When the roller 18 has been raised to the top of the incline the concentric portion of the cam engages with the roller during the continued forward movement of the cam and the latter does not shift the gear segments any further forward.

When the rear end of the concentric face 17 of the cam passes forwardly from underneath the roller 18, the constant pull of the springs

11 causes the rock-arm 13 to be depressed and the rock-arms 8 to be moved rearward. Upon now moving the cam 14 backwardly together with the rocking frame 15, this cam 5 does not affect the arm 13 and the parts connected therewith, but is affected by said arm at the last portion of the backward movement of the cam, at which time the back or lower side of incline 16 engages with the 10 roller 18 which lifts said incline, and at the end of the backward movement of the cam, the latter clears said roller and drops behind the same, as shown in Figure 2, preparatory to again raising the roller 18 and connecting parts during the next forward movement of the cam 14.

For the purpose of permitting the front end of the cam to rise so as to clear the roller 18, this cam is pivoted at its rear end to the 20 rear portion of the rocking frame 15. The upward and downward movement of the front end of the cam is limited by means of a lug 19 projecting from the side of the cam and engaging with a slot in the adjacent 25 part of the rocking frame 15, as shown in Figures 14 and 32.

The rocking frame 15, is secured with its lower portion to a transverse rock-shaft 20 journaled in the main frame and provided 30 outside of the frame with a hand crank 21, as shown in Figure 14, whereby this shaft is rocked and the parts connected therewith are operated.

The gear segments 5 are raised to their 35 highest position by means of a return or lifting bar 22 which extends transversely underneath all of the arms 6 of the gear segments and which is connected loosely at its rear ends with the transverse rod 7 by lifting plates 23. 40 24 represents two shifting arms which are mounted loosely at their rear ends on the rock-shaft 20 and which support at their other ends a transverse bar 25 which transverse bar is connected at its ends, by two 45 links 26, with the lifting plates 23, whereby upon raising the shifting arms 24, the lifting bar 22 is caused to raise the gear segments and the other parts connected therewith resting on said bar. Upon depressing the transverse 50 bar 25, the lifting bar 22 is moved downwardly and the gear segments resting thereon are permitted to move downwardly with the bar until the segments are arrested.

Each of the gear segments is yieldingly 55 held in contact with the lifting bar 22 by a spring 27 which connects the arm of the segment with the transverse bar 25. If the downward movement of the gear segment is arrested while the shifting arms 24 continue 60 to move downwardly, the lifting bar 22 is moved away from the underside of the arm of the gear segment and the spring 27 is strained. The transverse bar 25 is arranged in one end 65 in a segmental notch 28 formed in the front part of the rocking frame 15, shown in Fig-

ures 2, 7, and 14, and its opposite end is arranged in a similar segmental notch 28, formed in a rocking frame 29 (Fig. 14) which is secured to the operating shaft 20 on the left-hand side of the machine. The rocking 70 frames 15 and 29 together with the operating shaft 20 constitute the main or universal operating frame of the machine.

When the machine is at rest, as shown in Figure 2, the transverse bar 25 engages with 75 the front side of the notches 28 in the rocking frames 15 and 29. Upon turning the rocking shaft 20 forwardly by means of its handle 21 in the direction of the arrow, Figure 2, the rocking frames are moved forwardly during the first part of the movement independent of the transverse bar 25. The latter remains at rest until the inclined front end 16 of the cam 14 has raised the arm 13 and moved the gear segments, during which 80 movement the rocking frames move idly the extent of their notches 28 along the ends of the bar 25 without disturbing the latter. After the gear segments have been moved forward the continued forward movement 85 of the rocking frames causes the rear ends of their notches 28 to engage with the bar 25 and depress the same, thereby causing the lifting bar 22 to be moved downwardly and strain the springs 27. This causes all of the 90 gear segments which are free, to be moved downwardly and to continue their downward movement until they are arrested. After the segments have been arrested in their downward movement, they remain in this 95 position while the locking frames complete their forward movement. At the end of the forward movement of the rocking frames, the roller 18 of the rock arm 13 drops off from the rear end of the concentric part of 100 the cam 14, thereby allowing the springs 11 to pull the gear segments rearwardly.

Upon now turning the rock-shaft 20 backwardly by means of the handle 21, the rocking frames are moved backwardly until the 110 front ends of the notches engage with bar 25. When the latter is so engaged it is moved backwardly with the rocking frames to the end of their rearward movement which causes the transverse bar 25 to lift the lifting bar 115 22 and the gear segments which have been depressed, into their highest or normal position.

30 represents a number of elbow-shaped controlling arms, which form part of the devices whereby the downward movement of the gear segments is controlled. One of these arms is arranged along the left-hand side of each gear segment and consists of an upright front part and a horizontal lower part which 120 extends rearwardly from the lower end of the upright part, thereby leaving a clear space in rear of the upright part of the controlling lever, as represented in Figures 1, 2, 7, 13, 33 and 34. The rear end of the lower 130

part of each controlling arm is mounted loosely on a transverse supporting bar 31, while the upper end of its front or upright part is loosely connected with the upper portion of its companion gear segment. This loose connection permits the controlling arm and the gear segment to swing freely about their individual axes, which are arranged parallel but out of line, and also permits the gear segment to move forward and backward. In the uppermost position of the controlling arms the same bear with their upper ends against a transverse stop bar 32, as shown in Figure 2, which limits the upward movement of these arms. Each controlling arm is provided on the rear part of its upper end with a locking lug 33, and on the front part of its upper end with a stop lug 34, both of which lugs project toward the left and are preferably stamped out of one piece with the controlling arm.

The operation of the recording devices is controlled by a number of elbow-shaped key levers which are arranged side by side and pivoted to a transverse supporting rod 35. Each key lever is provided with a lower actuating arm 36 which projects forwardly and an upper stop arm 37 which projects upwardly along the left hand side of one of the controlling arms and gear segments, as represented in Figures 2, 7, 13 and 33. Each of these key-levers is provided on the rear side of its stop arm with a locking shoulder 38 which is adapted to engage with the locking lug 33 of the controlling arm when the latter is elevated into its highest position and the key-lever is in its fully retracted position, as shown in Figure 2. When the parts are in this position, the key lever holds the controlling arm against downward movement and the latter holds the gear segment against downward movement. If the gear segment while so held against downward movement is moved forward, and the rocking frames are turned forwardly for depressing the gear segment, the spring 27 of this segment will be strained without, however, shifting the segment. At the end of this forward movement of the rocking segments, the roller 18 of the rock arm 13 drops off from the rear end of the cam 14, the gear segment is moved rearwardly, and then the rocking frames move backwardly.

The upper arm of each key lever is provided on its front side with a vertical series of differential stop shoulders 39, which are arranged step fashion and extend from the upper end of this arm downwardly and forwardly thereon or in other words the stop shoulders 39 are arranged radially out of line with one another and different distances from the pivot of the key lever. These stop shoulders of the key lever are adapted to be moved forward into the path of the stop lug 34 on the controlling arm. The stop shoul-

ders are arranged different distances from the stop lug 34 of the controlling arm, so that by moving different stop shoulders of the key lever into the path of the stop plug of the controller arm, the latter and the gear segment connected therewith may be arrested at different points in their downward movement. The uppermost stop shoulder of the key lever is most remote from the stop lug of the controlling arm and therefore requires the greatest forward movement of the key lever, in order to bring this stop shoulder into the path of this stop lug.

The stop shoulders of the key levers are so arranged that the distance from the stop shoulders to the path of the stop lug 34 gradually grows less from the uppermost stop shoulder to the lowermost stop shoulder. By turning the key lever forward more or less and moving one or the other of its stop shoulders into the path of the stop lug 34 of the controlling arm, the distance which this arm descends can be varied, thereby varying the number of spaces which its gear segment turns.

Main number key mechanism

40 represents the main keys whereby the key levers of the main recording mechanism are operated, and which are guided with their depending stems in the top 41 and bottom 42 of the key-board. As shown in the drawings, nine longitudinal columns of these keys are arranged transversely side by side. The first column on the right hand side of the machine contains eight keys and represents fractions of one-eighth of a cent, the next column toward the left contains nine keys and represents cents and the remaining columns of keys toward the left each contains nine keys and represents progressively higher orders of numbers according to the decimal system, so that the registering keys in the last or left hand column represent hundreds of thousands of dollars.

The lowest number of the several columns of keys are arranged transversely in a row on the rear part of the keyboard and the corresponding higher numbers of the several columns are arranged likewise in transverse rows and progressively in their order toward the front end of the keyboard.

Each of the registering keys is yieldingly held in an elevated position by a spring 43 surrounding the stem of the key and connected at its upper end to the key and bearing with its lower end against the bottom of the keyboard. The upper movement of each key is limited by a shoulder 44 formed on the upper part of its stem and engaging with the underside of the top of the key-board, as represented in Figures 20 and 22.

The downward movement of all of the keys is substantially the same, but the arrangement of each column of keys lengthwise of the lower actuating arm of each key lever

causes the keys to bear against the lever at different distances from its pivot so that by depressing different keys the same distance, the key lever will be turned different distances. The keys having the lowest numbers bear against their respective key levers nearest the pivot and consequently the levers are thereby thrown the greatest distance, and the uppermost stop shoulders are shifted into the path of the stop lug 34 of the respective controlling arms. The throw of each key lever upon depressing any one of its keys is so adjusted that the proper stop shoulder on its upper arm is moved into the path of the stop lug 34 of the controlling arm and the downward movement of the respective gear segment is arrested after having turned a number of spaces corresponding to the number of the key which is depressed.

20 A slip or loose connection is provided between the controlling arms and the gear segments of higher denominational order which in the parent application is utilized for carrying in the accumulating mechanism. However, in the present application such slip connection might be dispensed with and any means provided whereby the gear segments may drive the controlling arms.

As shown in Figures 1, 2, and 7, each controlling arm is provided at its upper end with upper and lower guide faces 47 and 48 and its lower guide face is engaged by a lower guide lug 46 on the adjacent gear segment, the same as in the coupling between the controlling arm and the segment of the initial registering device.

When a key lever is actuated and the machine operated, the controlling arm related to said key lever descends until stopped by said key lever, and during the last portion of the operation the controlling arm and key lever are returned to their normal positions.

When the controlling arm has been retracted to its highest position, the adjacent key lever is moved into its normal retracted position, so that its locking shoulder 38 engages with the locking lug 33 of the controlling arm and locks the latter against downward movement. The return movement of each key lever is preferably effected by a spring 60 which connects the upper arm of the key lever with the transverse shaft 9, as shown in Figures 2 and 7, or some other convenient part of the machine. The lower guide lug of the gear segment is not absolutely necessary because the weight of the parts connected with the controlling arm and arranged in rear of its pivot is sufficient to raise the arm, but it is preferable to employ this lower guide lug 46 on the gear segment because it compels the arm to raise with the gear segment and avoids displacement of these parts with reference to each other, and also serves as a stop to limit the upward movement of the gear segment.

Recording mechanism

For the purpose of recording numbers, a recording mechanism is provided which is constructed as follows:

140 (Figs. 1, 2, 7, 9, 14, etc.) represents a printing roller or platen which is arranged transversely in the upper, rear part of the machine and under the lower side of which the sheet or other article is placed which receives the record. 141 represents a number of type segments which are arranged transversely side by side below the platen and which are pivoted at their front ends to the supporting bar 31 upon which the rear ends of the controlling arms are pivoted. Each of these type segments is provided at its rear end with a segmental row of type carriers 142, which are capable of moving radially back and forth on the type segment.

Each of the type carriers is provided at its rear end with a type and is guided upon the type segments by means of screws or rivets 143 (Figs. 3, 29 and 30) secured to the type carrier and arranged in radial slots 144 formed in the type segment. Each of the type carriers is held in its inward or retracting position by means of an S-shaped spring 145, which is arranged between the carrier and the type segment and is secured with one end to the carrier and with its other end to the type segment, as shown in Figures 29 and 30. Upon raising or lowering the type segment any one of its type can be brought to the printing point or line, and upon striking the back or inner end of the type carrier, when the same is in line with the printing point, the type carrier will be driven outwardly and its type will produce an impression on the sheet supported by the platen. After the carrier has received the blow for driving the same against the platen, the carrier is again quickly retracted to its innermost position by means of its spring.

Each of the type segments is connected with one of the controlling arms, so that upon depressing a controlling arm and the registering gear segment connected therewith, the companion type segment will be raised and present one of its type to the printing point.

For convenience in operating the machine, the keys are separated a considerable distance on the key-board and in order to produce a compact record, the printing segments are arranged closer together than the keys. In order to permit of this arrangement, each type segment and its corresponding controlling arm are connected by a connecting arm 146, as represented in Figures 1, 2 and 33. The connecting arms of the central controlling arms and type segments are comparatively straight, but the connecting arms of the outer type segments and controlling arms are arranged obliquely, the degree of this obliquity gradually increasing from the central type 130

segments and controlling arms in opposite directions toward the outer type segments and controlling arms, as represented in Figure 1. The connecting arms 146 of the outer controlling arms are arranged in the spaces behind the upright parts and above the horizontal parts of the controlling arms, thereby permitting the inner controlling arms to move up and down without interfering with the connecting arms 146 of the outer controlling arms.

The types on each type segment are arranged to correspond with the teeth and numbers of its companion gear segment, the zero type being at the upper end of the series and the progressively higher digits arranged in their order downwardly from the zero type. When the registering gear segment is in its highest position, the type segment which at this time is in its lowest position presents its zero type to the printing point. Upon depressing a gear segment, its companion type segment is raised proportionately and presents a correspondingly higher numbered type to the printing point.

147 represents a number of hammers whereby the type carriers are struck for driving the type against the platen. One of these hammers is arranged adjacent to each type segment and is provided with a head which is arranged in front of the series of types and in line with the printing point of the platen. Upon shifting the type segment so as to bring one or another of its type carriers to the printing line and then operating the hammer, the latter delivers a blow against the inner end of the particular carrier which is at the printing point and produces an impression of its type on the platen. The several hammers are pivoted on the transverse rod 12, arranged in rear of the segments; and each of the hammers is yieldingly held in its forward position by a spring 148 connected at its lower end to a cross bar 149 and at its upper end to a depending arm 150 on the hammer.

151 represents a vertically movable trip bar or rod which is arranged transversely below the hammers and whereby the latter are operated. This bar is supported at its ends upon the rear ends of rock arms 152 which turn loosely with their front ends on the rod 31 supporting the type segments and controlling arms.

153 represents a number of hammer or trip pawls, whereby the hammers are retracted preparatory to delivering a blow against the type carriers which are at the printing point. One of these pawls is arranged adjacent to each hammer and pivoted loosely at its lower end to the trip bar 151, and its upper end is provided on its rear side with a downwardly facing hook or shoulder 154, and above said shoulder with a trip face 155; as shown in Figures 3, 6 and 41. Each of the hammers is provided in front of its pivot adjacent to the

upper end of the hammed pawl with a lower trip lug or shoulder 156 and an upper trip lug or shoulder 157. When the parts are at rest, the hammer pawl 153 is raised into its highest position and the hammer is in its normal position with its lower trip lug 156 below and in rear of the hook of the hammer pawl and with its upper shoulder 157 in rear of the trip face of the hammer pawl, as represented in Figures 2, 3 and 41.

Upon shifting the hammer pawl rearwardly, while the parts are in this position, so that its hook overhangs the lower shoulder 156 of the hammer, and then pulling the hammer pawl downwardly, the hook of the hammer pawl engages with the lower shoulder of the hammer and turns the same so that its head is retracted from the type carrier at the printing line. As the hammer moves downwardly with the hammer pawl, the upper shoulder of the hammer comes into engagement with the trip face of the hammer pawl and during the continued downward movement of the hammer and its pawl, this upper shoulder gradually crowds the hammer pawl forwardly with reference to the hammer by reason of the hammer and its pawl swinging on different centers. During the last portion of the downward movement of the trip bar 151 and the hammer pawl mounted thereon, the pawl is crowded forwardly by the upper shoulder 157 of the hammer to such an extent that its hook is disengaged from the lower shoulder 156 of the hammer, thereby liberating the latter and permitting its spring 148 to throw the same quickly and deliver a blow against the type carrier at the printing line. The trip bar 151 now rises and carries the hammer pawl into its highest position, preparatory to again engaging the hammer for depressing the same.

158 (Fig. 3) represents a number of upright shifting arms whereby the hammer pawls are moved rearwardly, so that their hooks engage with the lower shoulders of the hammers. One of these arms is arranged adjacent to each hammer pawl, as shown in Figures 3, 6 and 41, and is pivoted at its lower end on the trip bar 151, and its upper end is provided with a roller or projection 159 which bears against a hammer cam 160 on the lower part of the adjacent type segment, as shown in Figures 3 and 7. This hammer cam is provided at its upper end with a receding or low portion, an inclined portion arranged below the low portion, and a concentric or high portion arranged below the inclined portion. Each shifting arm 158 is moved forwardly and its roller is yieldingly held in engagement with the adjacent hammer cam by a spring 161 connecting said arm with a cross bar 162 secured to the rock arms 152, as represented in Figures 7 and 8. The backward movement of each hammer pawl with reference to its companion shifting arm, is limited

by means of a stop 163 secured to the upper portion of the hammer pawl and engaging with the front side of the shifting arm, as represented in Figures 3, 5 and 41.

5 Each hammer pawl is yieldingly held in its rearmost position with reference to its shifting arm by means of a C-shaped spring 164 secured with its ends, respectively, to the hammer pawl and its shifting arm, as shown in Figures 2, 3 and 41. In the lowermost position of a type segment the receding part of its cam is presented to the roller of the shifting arm 158, which permits the hammer pawl to be retracted into its foremost position, as 10 represented in Figure 2. Upon depressing the trip bar 151 when the parts are in this position, the roller 159 is not engaged soon enough by the incline of the cam 160 to engage the hook of the hammer pawl with the lower shoulder of the hammer, before the hook has passed below this shoulder; but instead, the trip face of the hammer pawl slides 15 idly against the shoulder 156 without retracting the hammer, whereby no impression of the 20 particular type at the printing line is produced. If the type segment is raised, so as to present one of its lower types to the printing point or line, the incline of its cam, during the first part of the upward movement of 25 the segment, moves the shifting arm 158 rearwardly together with the hammer pawl yieldingly connected therewith, so that the hook of the hammer pawl stands over the lower shoulder 156 of the hammer. Upon now de- 30 pressing the pawl 153 the hammer will be retracted and released near the end of the downward movement of the pawl, and will be quickly swung up by the spring 148 thereby 35 delivering a blow against the type at the printing point and producing an impression 40 thereof.

The incline 160 of the type segment cam is so constructed that it throws the hammer pawl backwardly into an operative position 45 when the segment is raised one digit space, and during the continued upward movement of the segment, the hammer pawl is held in this operative position by the high concentric part of the segment cam. By thus construct- 50 ing the type segment cam its companion hammer pawl is not shifted when the segment is not raised and its zero type remains at the printing line, but the hammer pawl is shifted into an operative position for producing 55 an impression, if the type segment is raised one or more digit spaces and presents any one of its digits higher than zero to the printing line.

Automatic printing of zero

60 165 (Figs. 3 and 41) represents a number of transfer or coupling fingers which enable the ciphers in a number to be printed automatically. One of these transfer fingers is 65 secured to each of the shifting arms 158, as

represented in Figures 3, 7, and 41, and extends laterally toward the right therefrom in front of the shifting arm of the next lower hammer pawl, as represented in Figure 22. If any one of the printing segments remains 70 in its lowest position, so that its cipher remains at the printing line and the next higher printing segment has been raised for printing a higher number or digit, the transfer finger of the higher hammer shifting arm 158 75 while being moved rearwardly by the cam of its companion printing segment, is caused to engage with the shifting arm 158 of the next lower hammer pawl and shift the latter backwardly, so that its hook is carried backwardly over the lower shoulder of the companion hammer. Upon now depressing the trip bar 151, the higher hammer pawl 153 is coupled with its hammer, whereby an impression of the cipher or zero type on the lower 80 segment is produced on the platen at the same time that the next higher number is printed 85 on the platen.

If two ciphers occur in succession in the body of a number, the shifting arm to the left 90 of the highest order printing segment to be operated for printing a zero sets the hammer mechanism of said highest zero-printing segment by means of the transfer finger of said shifting arm, and the shifting arm of said highest zero-printing segment in turn by 95 means of its transfer finger sets the hammer mechanism of the printing segment of next lower order, etc. This operation of producing an impression of the cipher type is ef- 100 fected automatically and renders it possible to print any number of ciphers in succession in the body of a number because the hammer operating mechanism of each segment which remains standing with its upper type at the printing line is controlled by the hammer operating mechanism of a higher type seg- 105 ment and in turn controls the hammer operating mechanism of the next lower type segment, if the next lower segment presents a 110 cipher to the printing line.

Only the ciphers below the highest digit in the number to be recorded are thus printed automatically because the printing of a digit depends upon the upward movement of 115 a printing segment, thereby avoiding the printing of ciphers ahead of the highest digit in the number to be recorded. The hammer shifting device of the segment which prints the numbers representing units of cents is, 120 preferably, not provided with a transfer finger to operate on the hammer shifting device of the segment which prints fractions of a cent, because it is proper that the space to the right of the lowest integer shall remain blank 125 when no integer is recorded therein.

The trip bar 151 is raised by one or more springs 166 (Fig. 8) which connect this bar with the transverse rod 12, and the upward movement of the bar 151 is arrested when 130

- the hammer operating pawls reach their highest position by a transverse bar 107 (Figs. 8, 9, and 16) which is engaged by the rear ends of the rock arms 152. 168 represents a coupling hook, whereby the hammer trip devices are depressed. This hook is pivoted with its upper end to the trip bar 151 and its lower engaging end is provided with a notch having upper and lower shoulders.
- 10 In the lowered position of this hook its notch engages with a cross bar 169 which is connected with the rock arms 24, as represented in Figures 2 and 7, so that the hook and the hammer operating devices connecting therewith are actuated from the rocking frames 15 and 29, through the medium of the rock arms 24. In the rearmost position of the rocking frames, the front ends of their notches 28 bear against the front side of the bar 25 to which the gear segments are yieldingly connected, and the cross bar 169 bears against the rear or upper shoulder of the notch of the hook 168, as represented in Figure 2.
- 15 Upon swinging the rocking frames forward, the incline of the cam 14 first raises the rock arm 13 and shifts the gear segments into engagement with the dial pinions, and after the segments have been so shifted, the rear shoulders of the notches 28 in the rocking frames engage with the cross bar 25, so that thereafter this bar is carried downward with the rocking frames and the gear segments are depressed. During this downward movement of the bar 25 with the rocking frames, the companion bar 169 moves down idly in the notch of the hook 168 until this bar engages with the lower or front shoulder of this hook. After the cross bar 169 engages with the lower shoulder of the notch of the hook, the latter and the hammer operating devices connected therewith are moved downward with the rocking frames until these frames reach the end of their downward movement. During the last portion of the downward movement of the rocking frames the hammer pawls are disengaged, as before described, from the retracted hammers, whereby the latter are released and strike the type carriers which are at the printing line. By this means, the blow of the hammers is delivered after the type segments have been shifted into their proper position for recording the respective number.
- 20 The hammers do not follow the type carriers to the end of their outward movement but are stopped short, after delivering a blow against the inner ends of the carriers by their depending arms 150 engaging with a rubber facing 170 on the cross bar 167, as shown in Figure 3, so that the type are moved outwardly by the impact of the hammers and are then returned by their springs so as to 25 clear the printing surface.

Non-print mechanism

When it is desired to render the recording mechanism ineffective, the coupling hook 168 is raised with its notch out of engagement with the cross bar 169, which allows the rocking frames and connecting parts to move back and forth without affecting the hammer operating devices. The coupling hook is disengaged from the cross bar by means of an elbow lever 171 secured to a transverse rock shaft 172. The lower arm of the elbow lever is connected with the shaft 20 by a spring 173, whereby the lever and the shaft carrying the same are turned in the direction for disconnecting the upper arm of the lever 171 from the hook 168, thereby permitting the latter to engage the bar 169.

174 (Fig. 9) represents an elbow lever arranged below the bottom of the keyboard and having its lower arm connected by a line or cord 175 to the upper arm of the elbow lever 171. 176 represents a shifting key having a depending stem which is guided in the top and bottom of the key-board and which engages with its lower end against the upper arm of the elbow lever 174. Upon depressing this key the elbow lever 174 is turned in the direction for moving the rock arm 171 into engagement with the coupling hook 168 and disengaging the latter from the cross bar 169, thereby throwing the recording mechanism out of gear. Upon releasing the key 176, the rock arm 171 is permitted to swing backwardly and allow the coupling hook to engage with the cross bar 169, thereby throwing the recording mechanism into gear.

Duplicate printing by counterpart types

For the purpose of permitting the numbers to be printed in duplicate, for instance, when it is desired to print an amount on a bank check, and the same amount on a stub, the machine is provided with a mechanism which is constructed as follows:

1410 (Figs. 1, 14 and 16) represents a number of duplicate printing or type segments which are arranged transversely in line and preferably toward the right of the main printing segments 141, and which are pivoted loosely at their front ends on the supporting rod 31. One of these duplicate number printing segments is provided for each of the main number printing segments, and each duplicate segment is connected with its companion main segment by a U-shaped frame (Fig. 18) which frame is connected by the upper ends of its arms 189 to its duplicate and main segment and has its cross bar 190 arranged transversely below the intervening segments, as shown in Figures 1, 2, 4, 7 and 18. The cross bars 190 are arranged sufficient distances below the segments so that each pair of connected main and duplicate 130

printing segments can be raised to its highest position without interfering with the other segments. For the purpose of permitting the connecting frames of the several pairs of printing segments to be arranged compactly, the arms of the connecting frame are curved concentrically with the pivots of the segments, as represented in Figures 2 and 4.

- 5 Each of these duplicate printing segments is provided with type carriers corresponding to and constructed the same as the type carriers of its companion main segment and each of these duplicate segments is provided with a hammer operating device which is constructed the same as the hammer operating devices of the main segments, and the same description and letters of reference, therefore apply to the details of both the main and duplicate printing segments.

Duplicate printing inoperative

If it is desired to duplicate only the small numbers no duplicate segments need be provided for the higher numbered printing segments. For the purpose of throwing the duplicate printing mechanism out of gear when it is not desired to print the numbers in duplicate a horizontal movable bar 191 (Fig. 19) is provided which is arranged transversely in rear of the hammer pawls of the duplicate printing segments and which is provided with a number of forwardly projecting lugs or stops 192, as represented in full lines in Figures 4, 16 and 19. Upon shifting this bar, so that its stops stand in rear of the duplicate hammer pawls, as shown in full lines in Figure 19, these pawls are prevented from being swung rearwardly and operating the hammers. Upon moving this bar so that its stops clear the duplicate hammer pawls, as represented by dotted lines 192a, Figure 19, these pawls are free to be swung rearwardly by the segment cams 160 into engagement with the hammers, so as to retract the same during the downward movement of the pawls for producing an impression of the types of the duplicate segments which are at the printing line. A suitable key or finger-piece is provided, by the operation of which the bar 191 is shifted into effective position.

Horizontal ruling

- 55 For the purpose of producing horizontal or cross ruling upon the sheet or surface which receives the record, the following mechanism is provided:

193 (Figs. 2, 7, and 17) represents the lowest type carrier of each of the number printing segments, each of which is provided at its rear end with a horizontal ruling type. Each of these ruling type carriers is constructed the same as the number type carriers with the exception that the front end

of each ruling type carrier is widened horizontally, preferably, in both directions in the form of the letter T, as shown in Figure 17 and the ruling type extends transversely from end to end of the widened part of this carrier, so that the ruling types, when placed transversely in line and driven against the platen, will produce a practically continuous line transversely on the recording surface. Each of the number key levers is provided on the front side of its upper arm with a ruling stop or shoulder 194, which is arranged one space below the lowermost number registering stop or shoulder 39.

Upon swinging the key levers, so as to bring their ruling shoulders 194 into the path of the lugs 34 of the controlling arms, the latter together with the gear segments connected therewith are depressed upon moving the rocking frames 15 and 29 forwardly, until the stop lugs 34 of the controlling arm engage with the lowermost or ruling shoulders 194 of the key levers. When the controlling arms reach this lowermost position, the printing segments connected therewith have been raised to their highest position and present the ruling types of all of the segments to the printing line. During the last portion of the forward movement of the rocking frames 15 and 29, while the ruling types are at the printing line, the proper hammers are operated for producing an impression of these types.

The key levers are turned simultaneously for bringing all of their ruling shoulders simultaneously into the path of the stop lugs of the respective controlling arms by means of a rocking plate 195 which is arranged transversely in front of the lower arms of the key levers and overhangs the front ends thereof, as represented in Figures 2, 7 and 22. This rocking plate is secured to a transverse rock shaft 196 which is journaled in the frame of the machine and which is turned for holding the rocking plate in its uppermost position out of engagement with the key levers by means of a spring 197, as shown in Figure 22.

198 (Fig. 9) represents a shifting key, whereby the parts are shifted to permit of producing cross or horizontal ruling. This key is provided with a depending stem which is guided in the top and bottom of the keyboard and which engages against the rear end of a rock arm 199 projecting rearwardly from the rock shaft 196, as represented in Figure 9. Upon depressing this key, the rocking plate 195 is turned in the direction for depressing the front arms of all the number key levers and bringing the ruling shoulders 194 on the upper arms thereof into position for arresting the type segments during their upward movement when the ruling types arrive at the printing point.

In order to prevent the gear segments from moving forward during the cross ruling operation the position of the cam 14 is reversed

130

at the same time that the plate 195 is depressed.

The mechanism whereby cam 14 is reversed is constructed as follows:

5 The cam 14 drops into its operative position by gravity, and is provided in rear of its pivot with a tail 75 which is depressed when it is desired to lift the cam into its inoperative position.

10 76 is a shifting lever which is pivoted at its lower end and is normally turned so that its upper end is disengaged from the rear side of the tail on the cam 14, by a spring 77, as shown in Figures 2 and 7. 82, Fig. 9, represents a line or cord connected to lever 76 above its pivot, and 1961 represents a line or cord for operating cord 82.

15 In the parent application several cords operate the cord 82, but for the purpose of the 20 present application, the members 82 and 1961 might be a single cord.

The cord 1961 is connected to arm 1960 fast on a shaft 196, operable by the cross rule key 198.

25 When it is desired to produce horizontal ruling on the recording surface, the key 198 is depressed, thereby raising the cam 14 into an inoperative position, and moving all the 30 number key levers with their ruling shoulders 194 into the paths of the stop lugs of the controlling arms. Upon now moving the handle 21 (Fig. 14) forwardly the consequent rocking of the frames 15 and 29 first causes the 35 gear segments and their controlling arms to be moved downwardly until arrested by the ruling shoulders 191 of the key-levers, in which position of the parts, the printing segments have been raised with their ruling types to the printing line. The continued 40 forward movement of the rocking frames operates the hammer-tripping mechanism and produces an impression of the ruling types on the record surface; upon moving the handle 21 backwardly the parts resume 45 their normal position.

Instead of producing cross ruling by means of a transverse row of independent types, this 50 ruling may be effected by a separate ruling plate 200 (Fig. 37) which extends transversely along the entire width of the space to be ruled. In this modified construction of the 55 horizontal ruling device, the ruling plate may be supported by upright arms 201 from a transverse bar or shaft 202, and may be operated by any suitable mechanism.

Vertical ruling

60 Mechanism is provided whereby vertical ruling may be produced on the recording surface, this mechanism being constructed as follows:

65 203 (Figs. 1, 14, 16, and 28) represents an upright ruling lever which turns loosely on the supporting bar 12 and which is arranged between the dollars and dimes printing seg-

70 ments: The upper arm of the ruling lever is provided with a vertical ruling blade 204 (Fig. 28) which is arranged close to the platen when in its upper position. The ruling lever is yieldingly held in this position by means of a spring 205 connected with the lower arm of the ruling lever and the movement of the latter toward the platen is limited by the engagement of its lower arm with the rear side of a rubber buffer 206 on the cross bar 167 75 similar to the rubber 170. 207 represents a pawl whereby the ruling lever is retracted and then released for permitting the same to deliver a blow against the recording surface for producing a vertical ruling impression thereon. This pawl is pivoted at its lower end on the cross bar 151 and is yieldingly held with the hook 208 on its upper arm in engagement with a shoulder 209 on the ruling lever by means of a spring 210 which connects the lower arm of the ruling lever with the rod 162.

80 In the uppermost position of the bar 167 the ruling pawl engages the shoulder of the ruling lever and upon depressing this bar, 90 the ruling lever is pulled downward by the ruling pawl. During this downward movement of the ruling lever and pawl, the front side of this lever engages with the upper arm of the pawl and gradually crowds the pawl forward until the pawl is disengaged from the shoulder of the lever. When the ruling lever is thus released from the pawl, the lever is quickly turned by the spring 205 in a direction for throwing its upper arm upwardly, 100 whereby its blade delivers a blow against the recording sheet or surface on the platen and produces a ruling impression thereon. During the last portion of the subsequent upward movement of the ruling pawl 207 its hook 105 again engages over the shoulder of the ruling lever. This construction of vertical ruling devices produces the vertical ruling in sections by successive blows of the ruling blade.

110 If desired vertical ruling may be produced by holding a stylus or lead pencil 211 against the recording surface by means of a stationary holder 212, as represented in Figure 38, whereupon continuous ruling is produced on the recording surface or sheet as the sheet 115 is fed past the same.

Vertical ruling may also be produced by a 120 ruling disk 213 arranged to bear with one side against the recording surface and an ink-ing wheel 214 supplying the ink to the edge of the ruling disk, as represented in Figure 39.

Word printing mechanism

125 For the purpose of permitting words to be printed in front of the numbers the following mechanism is provided:

130 1411 (Figs. 1, 8, 14 and 16) represents a word printing segment which is mounted loosely on the rod 31 next to the highest number 130

printing segment of the main number recording mechanism. This segment is provided with a number of radially movable carriers 1420, (Figs. 8 and 16) which are constructed the same as the carriers of the number printing segments and each of which is provided on its face with a word-type. The words of these types are selected according to the purpose or business for which the machine is to be used. For instance, if the machine is to be used in a bank, types representing the words "Vouchers", "Checks", "Drafts", "Bills", and similar words common to the banking business may be used. When the machine is designed for use in a restaurant, the words "Soup", "Vegetables", "Meats", "Dessert", and other words peculiar to this business may be used.

The position of the word-type segment is controlled by a key lever 3600, Figure 8, which turns on the bar 35, is similar to the number key levers, and is provided on the front side of its upper arm 3700 with a vertical series of differential stops or shoulders 3900 which are adapted to be engaged by the stop lug 3400 of a controlling arm 3000; and lever 3600 is also provided with a locking stop or shoulder 3800 which is adapted to be engaged by a locking lug 3300 on the controlling arm, as represented in Figure 8. The controlling arm 3000 is connected with the word-printing segment by a connecting bar 1460. The stop shoulders on the upper arm of the word-key lever are so arranged that upon swinging this lever so as to carry different shoulders into the path of the stop lug on the controlling arm, the latter will be arrested at different points in its downward or forward movement and the word-printing segment connected therewith will be stopped at different points in its upward movement and present the particular word type to the printing point which corresponds with the shoulder or stop on the word-key lever.

The upward movement of the controlling arm 3000 is limited by its rear locking lug 3300 engaging with the stop bar 32 which arrest the upward movement of the controlling arms 30 of the auxiliary recording mechanism. The downward movement of the controlling arm 3000 and the simultaneous upward movement of the word printing segment is effected by a spring 215 which yieldingly connects this arm with the bar 25 to which the registering gear segments are connected.

216, Fig. 1, represents a row of word-keys having depending stems which are guided in the top and bottom of the keyboard and which engage against the upper side of the front arm 3600 of the word key lever at different distances from the fulcrum thereof. Upon depressing any of the word keys, the word-key lever will be turned the proper distance to bring its proper stop shoulder into

the path of the stop lug of the companion controlling arm and arrest the word-type segment during its upward movement, when the word-type corresponding with the word of the depressed key has reached the printing line. When the respective word-type is in this position the same is driven against the recording surface for producing an impression thereon, at the same time that the printing of the numbers by the numbering printing segments, is effected. The word-types are driven against the platen by a hammer-operating mechanism which is constructed the same as the hammer-operating devices of the number printing mechanism, and the same letters of reference are therefore used to denote the same. The word-key lever is yieldingly held in its normal position by a spring 600.

Auxiliary printing mechanism

An auxiliary printing mechanism is provided which permits of recording numbers different from the numbers which are recorded by the main recording mechanism. This auxiliary printing mechanism is constructed as follows:

5000 (Figs. 1 and 25) represents a number of auxiliary gear segments which are mounted on the transverse rod 7 and are movable forward and back therewith. Each gear segment 5000 is connected with a respective controlling arm 3001 (Figs. 1 and 25) in substantially the same way that the main gear segments are connected to their controlling arms, except that the auxiliary controlling arms are capable of moving independently of their correlated gear segments. This last feature, however, forms no part of the present invention.

3601 (Figs. 9 and 22) and 3701 (Figs. 1, 9 and 25) represent the lower and upper arms respectively of auxiliary key levers which are operated by auxiliary keys 401 (Fig. 1), and which control the operation of the auxiliary recording mechanism.

The detail construction of the gear segments, printing segments, key levers, and the parts co-operating therewith of the auxiliary recording mechanism, is substantially the same as the construction of analogous parts in the main recording mechanism, except as elsewhere mentioned, and the same letters of reference are therefore employed in most cases to denote like parts in both of these sets of mechanisms.

In the drawings, two auxiliary key levers and related parts are shown, but additional recording devices may be employed if it is desired to increase the capacity of the machine.

In the auxiliary recording mechanism the gear segments are not provided with lower stops 46 like those of the gear segments of the main recording mechanism, so that the auxiliary controlling arms may move down-

ward when necessary independently of the auxiliary gear segments. The upward movements of the auxiliary gear segments is limited by stops 218 (Fig. 25) with which the upper ends of the gear segments engage. 219 represents a foot formed on the lower side of each controlling arm 3001 and adapted to be lifted by the cross rod 22. 220 represents springs whereby the auxiliary controlling arms are connected with the cross bar 25.

For the purpose of recording numbers by the auxiliary mechanism, the auxiliary key levers are shifted into the proper position by the depression of the keys 401 representing the numbers to be added, and then the rocking segments 15 and 29 are turned forward. During the forward movement of the rocking frames, the auxiliary gear segments are first moved forward by cam 14, and are then pulled down by the springs 27, and the controlling arms 3001 are pulled down by springs 220 and the gear segments. The downward movement of the gear segments and the controlling arms continues until the stops 34 of the controlling arms strike the shoulders 39 which stand in the path of said stops 34. At the end of the forward movement of the rocking frames 15—29 the gear segments are moved rearward by the springs 60; and during the subsequent backward movement of the rocking frames, the gear segments and controlling arms are raised by the cross bar 22 bearing up against the gear segments and the feet 219 of the controlling arms.

By this organization of the machine, numbers representing sales or prices of goods can be recorded by the main recording mechanism, and other numbers representing rebate on sales or discount on the prices of goods can be separately recorded by the auxiliary recording mechanism.

From the foregoing description, it will be seen that the key-controlled devices whereby the parts of the main recording mechanism are shifted into the proper position preparatory to recording a number are distinct from the key-controlled devices whereby the same effect is produced in the auxiliary recording mechanism, but both sets of recording mechanisms are operated simultaneously by the one universal shifting mechanism for effecting recording of the numbers which are represented by the different positions of both key controlled devices.

231 is an upright shifting lever, Figure 16, whereby the operation of the printing mechanism of the auxiliary registering mechanism may be controlled. This lever is provided on its upper arm with a cross bar 232 which is arranged in rear of the hammer-retracting pawls of the auxiliary printing segments and its lower arm is connected by a wire or cord 233 (Fig. 9) with a thumb piece 234 which is guided in an opening in the front part of the frame. The lever 231 is turned by a

spring 235 (similar to spring 256, Fig. 26) in the direction for moving its cross bar forward against the auxiliary hammer pawls, thereby holding the same out of engagement with the hammers 147 of the auxiliary printing segments and preventing the same from effecting recording on the impression surface. Upon pulling the thumb piece 234 forwardly, the lever is turned so as to move its cross bar rearwardly away from the auxiliary hammer pawls, thereby permitting the same to engage the hammers of the auxiliary printing segments. The shifting lever is held in its operative or inoperative position by two shoulders 236, 237 arranged one behind the other on the thumb piece and adapted to engage with the edge of the opening in which the thumb piece is guided.

Indicator or detector dials

In order to enable the operator to see which particular character or characters the machine is set for printing after depressing the keys, and thereby detect any errors in the depression of the keys, each of the key levers is provided with an auxiliary dial indicator, or detector, 238 (Figs. 1 and 2) which is turned forward the same number of spaces that the key lever has been depressed and then returns to its initial position when the key lever moves backward into its normal position. In the preferred construction of the detector dials shown in Figures 1, 2, 7 and 13, each of these dials consists preferably of a wheel 238 provided on one side with a pinion 239 which is engaged by a gear segment 240 secured to the adjacent key lever, as shown in Figures 2, 7 and 13.

Upon depressing one of the number recording keys, the detector dial thereof is turned forwardly by the connecting gearing the same number of spaces corresponding with the number of the key which has been depressed. If a key lever is not depressed its detector dial remains at zero. The detector dial of the word-printing mechanism is in like manner turned by its key lever so as to indicate the word which corresponds to the word of the depressed key.

The detector dials of the several recording devices are mounted loosely on a transverse supporting rod 241.

In the modified construction of the detector dial shown in Figure 40, this dial is constructed in the form of a segment 242 which is connected by an arm 243 with a hub 244, and which is turned in one direction by gravity and in its opposite direction by a pin or lug 245 arranged on the adjacent key lever and engaging with an arm 246 on the hub 244. By means of these detector dials the operator can see which number and word is represented by the depressed keys, thereby enabling the same to be corrected if an error occurs before printing the same.

Date printing

For the purpose of permitting the date to be printed on the impression surface the following mechanism is provided:—

- 5 247 represents a year printing lever, Figures 1, 14, 16 and 27, which is arranged toward the left of the auxiliary numbering mechanism and which is mounted loosely upon the rod 12 which supports the hammers 10 of the printing segments. The upper arm of the year lever is provided with a year type 248 representing the year to be printed, and this lever is turned for moving its type 15 against the platen or the impression surface by means of a spring 205 secured to the lower arm thereof. The year printing lever is turned so that its type moves away from the platen and is then permitted to spring back 20 quickly so as to produce an impression of its type on the impression surface by means of an operating mechanism which is constructed the same as the operating mechanism of the vertical ruling blade 204, shown in Figure 28, and the same reference letters are therefore used 25 to denote like parts in these operating mechanisms.

249 (Figs. 1, 14, 16 and 26) represents three printing segments whereby the months and the days of the months may be printed and 30 which are arranged in the order named on the left hand side of the year printing lever.

Each of these segments is pivoted at its rear end on the same bar 31 which carries the other printing segments and is provided 35 with type carriers which are constructed the same as the type carriers of the other printing segments. The units dating segment is provided with ten digital type carriers. The tens dating segment which prints the days of 40 the month above 9 in connection with the units dating segment is provided with three type carriers bearing the numbers 1, 2 and 3. The months printing segment is provided 45 with twelve type carriers which are provided with type characters representing the different months in the year.

Upon shifting the several type or printing segments of the dating mechanism, so as to 50 carry the desired month and day of the month to the printing line the respective type may be driven against the impression surface for recording the date represented by the same. Each of the months and day printing segments is retained in its adjusted position by 55 means of a catch 250 projecting upwardly from the segment and engaging with the notches of a curved bar 251 secured to the adjacent stationary part of the machine, as 60 represented in Figures 1 and 26. The notches in each of these bars are spaced to correspond with the position of the type, and each of these notches is marked according to 65 the month or day of the month which it represents, as shown in Figure 1, for the purpose

of enabling the operator to readily set the dating mechanism.

Each of the dating segments is provided with a printing hammer which is constructed the same as the printing hammers of the other printing segments as shown in Figure 70 26. The printing hammer of each date printing segment is depressed by a pawl 252, shown in Figure 26, which, when free, is moved rearward by a spring 253 so that its shoulder or hook engages with the lower shoulder 156 of the adjacent printing hammer and pulls the latter downwardly when the bar 151 is depressed. When the bar 151 is 75 near the end of its downward movement, the pawl 252 is crowded with its hook from said lower shoulder by the upper shoulder 157 of the hammer engaging with the upper end of the pawl, thereby liberating the hammer and permitting the same to deliver a blow against the date-type carrier which is at the printing line, for producing an impression thereof.

Inasmuch as the printing of the date is not required frequently, the pawls of the month, day and year printing mechanism are held in an inoperative position when it is not desired to print the date, by means of a rock lever 254, as shown in Figures 9, 16, 26 and 27. This rock lever is provided on its upper arm with a cross bar 255 which is arranged transversely in rear of the several pawls of the dating mechanism. The rock lever 254 is turned by a spring 256, so as to move its upper arm forwardly and cause its cross bar to engage with the rear side of the pawls 207 and 252 of the dating mechanism and shift them into inoperative position, out of engagement with the lever 247 and hammers 147 respectively. While the dating pawls are in this position, the same move up and down idly without operating the date-printing mechanism, but the pawls of the other printing segments are free to operate.

257 (Figs. 1 and 9) represents a shifting key whereby the pawls of the dating mechanism are released and permitted to move into their operative position for printing the date. This key is provided with a depending stem which is guided in the top and bottom of the key-board and which engages with its lower end against the upper arm of an elbow lever 258, as represented in Figure 9. The lower arm of this elbow lever is connected by a line or cord 259 with the lower arm of the lever 254. Upon depressing the shifting key 257 its respective elbow lever shifts the rock lever 254, so that the cross bar on its upper arm moves rearwardly from the dating pawls and permits the latter to assume an operative position.

Platen mechanism

The mechanism whereby the platen is supported and operated and the record sheet or 130

other impression surface which receives the record is presented to the printing line, is constructed as follows:—

The frame of the carriage which supports the platen paper and inking device consists of a transverse supporting sleeve 260 (Figs. 2, 9, 12, and 15) arranged in rear of the type-controlling mechanism and provided at opposite ends with two upwardly and forwardly projecting arms 261 and with two upwardly and rearwardly projecting arms 262, as represented in Figures 1, 2, 9, 11, 14, 15 and 16. The supporting sleeve is arranged to slide transversely on a rod or track 263 which is secured with its ends to the sides 15 of the main frame 1.

The platen is journaled in the upper ends of the front arms 261 of the paper carriage and is held in position at the printing line by means of a catch 264, Figure 12, which engages with its front hooked end over a transverse rod 265 arranged below the platen and secured with its ends to the sides of the main frame, as represented in Figures 1, 2, 12, and 25 16. This catch is yieldingly connected with the paper carriage, so as to permit the platen to recede more or less from the printing types, for the purpose of adjusting the platen according to the thickness of the sheet or 30 sheets of paper or other object which receives the impression and which is interposed between the platen and the printing types.

As shown in Figure 12, this yielding connection between the paper carriage and its 25 retaining catch consists of a flat tension spring 266 which is secured with its lower end to the right-hand front arm 261 of the paper-carriage, and the retaining catch 264 is pivoted to the upper end of this spring 40 so as to turn in a vertical plane. The upper end of the tension spring 266 is provided with a thumb piece 267, and the adjacent end of the retaining catch is provided with a similar thumb or finger piece 268. The 45 paper carriage is swung forward until its front arms 261 strike the cross bar 265. The retaining catch, while moving forward with the carriage, rides with its inclined front end over the rod 265 and then engages with 50 the front side of this bar, thereby holding the paper carriage in its operative position.

If the article which receives the record is above normal thickness, the platen cannot be moved forwardly sufficiently to engage 55 the upper arms 261 with the cross bar 265. In order to hold the carriage in position while printing upon such an abnormally thick object, the upper end of the spring 266 is pressed forward by means of its finger piece 267 until the hook of the retaining catch engages with the cross bar 265. When 60 it is desired to inspect the writing on the record sheet or object, the upper end of the 65 paper carriage may be swung backwardly

from the printing mechanism by first pressing the tension spring 266 forwardly to ease the strain on the catch 264, and then turning this catch by means of its finger piece out of engagement with the cross bar 265, thereby leaving the carriage free to move rearwardly. The catch 264 is yieldingly held in engagement with the cross bar 265 by a spring 269 which is secured at one end to the main tension spring 266 and bears with its 70 opposite end against the rear end of the catch. 75

When printing upon a sheet of paper, this sheet is fed forwardly underneath the platen and upwardly in front of the same, so that the sheet passes the printing line. The sheet 80 is pressed against the under side of the platen, in rear of the printing line, by a transverse presser roller 270 arranged below the platen and journaled with its ends in the front arms 85 261 of the paper-carriage.

When it is desired to print upon a roll or web of paper, this roll is supported in rear of the platen and fed with its web around the platen in the same manner in which a sheet is fed. As shown in Figures 2, 9 and 12, an upper roll of paper is supported upon a divided spool consisting of two sections 271 which support opposite ends of the roll. 272 represents a horizontal supporting spindle which extends through the center of the upper roll of paper and through the sections of its supporting spool and which is supported at its ends in openings formed in the rear arms 262 of the paper carriage. This spindle 90 is held against displacement in the paper carriage by a catch 273 pivoted to one of said arms 262 and engaging with a notch or groove 274 formed in said spindle, as represented in Figures 10 and 11.

The paper roll may be held against longitudinal displacement on the spindle by any suitable means, for instance by engaging one of its spool sections against one of the rear carriage arms and securing a clamping collar 275 to the spindle and bearing against the outer side of the other spool section, as represented in Figure 10. By moving the sections of the roll-supporting spool toward and from each other on the spindle the spool can be adjusted to suit different widths of paper. 105 110 115

When it is desired to print the record in duplicate a duplicate roll or web of paper is fed simultaneously with the main sheet or web past the printing line. The duplicate 120 roll or web of paper is preferably supported below the main roll on the sections 276 of a divided spool which is mounted on a spindle 277. This roll spindle is supported at its ends by means of hangers or hooks 278 which engage with the ends of the rear arms of the carriage, as shown in Figures 9, 10 and 12. The lower spool is held on the spindle by a collar 279 and the lower spindle is held in 125 130 place on the hangers by a catch 280.

Paper guides

281 (Figs. 1, 2, 9, and 12) represents two paper guides which engage against opposite sides of the webs or sheets between the rolls 5 and the platen, and prevent lateral displacement of the same. Each of these guides is adjustably secured to the adjacent front arms of the paper carriage, preferably by means of a clamping screw 282 arranged on the adjacent carriage arm and engaging with a slot in the adjacent guide.

Platen feed or line spacing

15 283 (Figs. 9, 14 and 16) represents a platen feed lever which is pivoted loosely on the left end of the platen shaft and which is provided on its rearwardly projecting arm with a pawl 284 which engages with a ratchet wheel 285 20 secured to the adjacent end of the platen, as represented in Figures 1 and 9. 286 represents an intermediate actuating lever which is pivoted on the lower part of the front carriage-arm 261 which is adjacent to the 25 ratchet wheel 285. The ratchet lever is connected with the intermediate lever by means of a link 287 which is pivoted at its upper end to the rear arm of the ratchet lever and is provided at its lower end with a loop 288 30 which receives the rear arm of the intermediate lever. 289 represents a spring which connects the front arms of the ratchet lever and intermediate lever. The upper end of this spring is connected with the front arm of the 35 ratchet lever a greater distance from the pivot of the latter than the distance between the connection of this spring with the intermediate lever and the pivot of the latter. By this connection of the spring 289, the leverage of 40 the ratchet lever is greater than that of the intermediate lever, which causes this spring, when both of these levers are free, to turn these levers simultaneously in the direction for raising their rear arms, thereby moving 45 the ratchet pawl upward for taking up a new tooth on the ratchet wheel.

The ratchet pawl is yieldingly held in engagement with the ratchet teeth by means of a spring 290. The movement of the intermediate lever in the direction for raising its rear arm and moving the ratchet pawl backwardly is limited by means of a nose 291 50 formed on this lever and engaging with a stop on the adjacent arm of the carriage, as represented in Figure 9.

The rocking motion of the intermediate lever is always the same, and in order to enable the same to turn the platen different distances, the rear arm of the intermediate lever 55 is provided on its under side with a number of notches 292 which are arranged different distances from its fulcrum, and one or another of which is engaged by the lower end of the loop 288 on the connecting link 287. Upon engaging this loop with the notch of the in-

termediate lever nearest its axis, the ratchet pawl is shifted so that the platen is turned one line-space at a time; while upon shifting this loop into engagement with one of the outer notches of the intermediate lever, the platen will be turned forward by its ratchet mechanism a correspondingly greater distance by the operation of the machine. 70

The intermediate lever is turned in the direction for shifting the platen by a transverse bar 293 arranged below the front arm thereof, as represented in Figures 1, 2, 7, 9 and 16. This bar is supported upon the upper ends of two rock arms 294 which are mounted loosely at their lower ends on the cross bar 167. 295 (Fig. 9) represents a depending arm which is preferably formed in one piece with that one of the arms 294 arranged on the left hand side of the machine. This depending arm is provided with a nose 80 which is arranged in rear of and in the path 85 of the rocking frame 29.

During the last portion of the rearward movement of this rocking frame, it engages with the nose of the depending arm 295 and 90 moves the same rearwardly and the upper arms 294 connected therewith are moved forwardly, thereby causing the cross bar 293 to be carried upwardly and turn the intermediate lever in the direction for feeding 95 the platen and paper forwardly. During the forward movement of the rocking frame 29, the rock arms 294 are turned backwardly, together with the intermediate lever and connecting parts, by the spring 289 preparatory 100 to feeding the platen forward the next line space. As the line spacing of the record sheet by feeding the platen occurs after each item is printed and in the same operation in which said item is printed, the printed record is 105 fed up into visible position at each operation of the machine.

If desired, the platen may be turned by hand when it is desired to adjust the paper, this being effected by releasing the pawl 284 110 from the ratchet wheel and then turning the platen by means of a button 296 secured to one end of the shaft, as shown in Figures 1, 14 and 16.

The cross bar 293 extends a sufficient distance transversely of the machine so as to engage with the front arm of the intermediate rock lever 286 in all the positions to which the paper carriage can be shifted transversely 115 in the machine. 120

Non-print renders paper feed inoperative

In order to render the paper feeding mechanism inoperative during the time that the type-controlling mechanism is out of gear, the operating mechanism of the paper feeding mechanism is so connected that the type-controlling and paper-feeding mechanisms are thrown into and out of gear simultaneously. 125 130

A simple means for this purpose consists of a link 297 (Figs. 9 and 16) connected at its front end with a depending arm 298 on the rock shaft 172 and provided at its rear end with a slot 299 which receives a pin 300 on the depending arm 295. Upon turning the rock shaft 172, by means of the key 176, in the direction for engaging its upper arm 171 with the hook 168 (Fig. 2) and disengaging the latter from the bar 169, the link 297 is moved rearwardly so that the front end of its slot engages with the pin of the depending arm 295 and holds the latter in its rearmost position. While the depending rock arm is so held it cannot move forwardly with the rocking frame 29 and consequently the ratchet pawl of the paper feed mechanism does not move backwardly for taking up a new tooth on the ratchet wheel.

Upon releasing the key 176 the rock shaft 172 turns in the direction for coupling the type-controlling mechanism with the rocking segments, the link 297 is moved forwardly, and the front end of its slot is carried forwardly a sufficient distance to permit the rock arm 295 to oscillate freely for actuating the paper-feeding mechanism.

Horizontally movable carriage

The paper-carriage is capable of sliding lengthwise on the rods 263 and 265 for presenting different parts of the paper to any particular type and is held in its adjusted position by a spacing device which consists of a graduated adjusting sleeve 301 and an adjusting catch 302, as represented in Figures 2 and 15. The adjusting sleeve is revolvably mounted on the supporting sleeve 260 between the carriage frame arms 261 and is provided with two or more longitudinal series of stop notches or graduations 303, 304. The notches in each series may be equidistant and the notches in one series are spaced different from the notches in the other series, as shown in Figure 15. The catch 302 is pivoted on the rod 167 and is yieldingly held in engagement with any one of the notches in the adjusting sleeve 301 by a spring 305. When it is desired to shift the carriage intermittently short distances lengthwise of the platen for printing narrow columns, the adjusting sleeve is turned so as to present its closely spaced notches to the catch, and the latter is shifted from one of these notches to another as the printing progresses. When wider columns are to be printed the adjusting sleeve is turned so as to present correspondingly wider spaced notches to the catch. As shown in the drawings, only two series of adjusting notches are provided on the adjusting sleeve, but more series of notches may be provided if necessary.

If desired, sheet paper may be substituted for web paper, to receive the record, without changing the parts of the machine, but the

devices for holding the rolls of web paper may be removed from the machine when printing upon sheet paper.

Inking means

306, 307 (Figs. 1, 2, 9, and 14) represent two inking ribbons whereby the impression of the types at the printing line is produced simultaneously on the two sheets or webs of paper. The front or outer ribbon 306 is arranged in front of the outer or lower sheet and the rear or inner ribbon 307 is arranged between the front and rear sheets at the printing line, as represented in Figures 1, 2, 9 and 14. Each of these ink ribbons is wound with its opposite ends upon spools 308 and upon turning one of these spools in one direction, the ribbon will be wound thereon and unwound from the other spool and vice versa. The two spools on the same side of the machine are preferably arranged side by side and are journaled in bearings on the adjacent portion of the main frame, so that the spools of the front ribbon 306 are arranged adjacent to the inner sides of the spools of the rear or inner ribbon 307.

Each of the ink ribbon spools is provided on the front end of its shaft with a ratchet wheel 309, the ratchet wheels of the outer spools being arranged slightly forward of the ratchet wheels of the inner spools. 310 (Figs. 1 and 9) represents two ratchet levers whereby the ink ribbons are intermittently shifted lengthwise of the platen or transversely of the sheet. One of these levers is provided for each pair of spools and is provided at opposite ends with upwardly projecting hooks 311 which are adapted to engage with the ratchet wheels of its respective spools. 312 (Figs. 1, 2, 7, 9, and 14) represents a transversely reciprocating bar which is guided with its ends in the side portions of the main frame and which supports and operates the ribbon-operating ratchet levers. The ribbon ratchet levers are arranged on opposite sides of the reciprocating bar 312 and the latter is provided on its central portion with a pin 313 which engages at its front end with a slot 314 in the central portion of the front ratchet lever, and engages at its rear end with a similar slot 314 in the central portion of the rear ratchet lever, as represented in Figures 1, 2, 14 and 36.

Each of the slots 314 consists of two branches which are united at their lower ends and diverge upwardly in the form of the letter V. 315 (Figs. 2, 14 and 36) represents springs whereby the ribbon-shifting ratchet levers are yieldingly held in their operative position. Each of these springs is secured at its upper end to one of the shifting levers adjacent to the junction of its slot branches and with its other end to the adjacent part of the reciprocating bar. The tension of each of the springs 315 serves to draw the central

part of its ribbon-shifting lever downwardly so that the upper end of one of its slot branches engages with the pivot pin 313 of the same.

As shown in Figures 1, 14 and 36, the left-hand branch of the V-shaped slot of the front ribbon-shifting lever engages with its upper end against the pivot pin 313, and the connection between the spring 315 and this lever is now arranged on the right-hand side of the pivot pin, which causes the right arm of this lever to be swung downwardly with its hook out of engagement with the opposing ratchet wheel, while its left arm is raised and its hook is yieldingly held in engagement with the adjacent ribbon ratchet wheel. Upon reciprocating the bar 312 by the spring 316, lever 317 and connecting mechanism hereinafter described, when the parts are in this position, the left arm of the front ribbon-shifting lever is moved idly toward the left and its hook takes up a new tooth on the adjacent ratchet wheel and during the subsequent movement of the lever with the bar 312, toward the right, this hook turns the ratchet wheel and the spool connected therewith in the direction for winding the ribbon thereon. This operation of the front shifting lever is repeated during every reciprocating movement of the bar 312 thereby feeding the ribbon intermittently from the right hand spool to the left hand spool.

When the front ribbon has been wholly unwound from the right hand spool, the further movement of the ribbon toward the left is prevented by reason of the ribbon being connected with this spool. Upon moving the bar 312 toward the right while the right-hand end of the ribbon is thus held, the ribbon-shifting lever is prevented from moving toward the right with the bar, by reason of the hook of its left arm being in engagement with the ratchet wheel of the left-hand ribbon spool. When the ribbon shifting lever is thus arrested, the bar 312 moves toward the right independent of the lever and during this movement, the pivot pin 313 moves to the inner end of the left branch of the V slot and then outwardly in the right branch to the outer end thereof. By thus shifting the pivot pin 313 of the bar in the slot of the lever the connection between this lever and the spring 315 is carried toward the left side of the pivot pin, so that the relative position of the shifting lever and spring is reversed, as represented by dotted lines 310^a, 315^a, in Figure 36.

When this lever is so reversed, its right arm is turned with its hook into engagement with the ratchet wheel of the adjacent ribbon spool, and the left arm thereof is moved with its hook out of engagement with the ratchet wheel of the adjacent ribbon spool, whereby the movement of the ribbon is automatically reversed and the ribbon is caused to wind up on the right-hand spool and to unwind from

the left hand spool. The ribbon continues to move toward the right until wholly unwound from the left-hand spool to which it is connected, when the pivot pin 313 of the ribbon-shifting lever is shifted back to the upper end of the left branch of the V slot, and the movement of the ribbon is again reversed in the same manner as before described.

The front and rear ribbon-shifting ratchet levers are reversed independently of each other and can feed their respective ribbons in opposite directions although they are both operated from the reciprocating bar. The latter is moved lengthwise in one direction, preferably toward the right, by a spring 316, as shown in Figures 1 and 14. The ribbon-shifting bar 312 is moved in the opposite direction by an elbow lever 317 which engages with its upper end against a lug or shoulder on the bar. 318 (Figs. 1, 9, and 14) represents a rock arm which is secured to the rock lever 294, 295 of the paper-feed mechanism and which engages with the lower arm of the elbow lever 317. When the rock lever 294, 295 turns in the direction for feeding the paper forward, the arm 318 turns the elbow lever 317 and moves the ribbon shifting bar 312 toward the left, and when the rock lever 294, 295 turns in the opposite direction, the spring 316 moves the bar 312 toward the right. When it is desired to print only one sheet or web of paper one of the ink ribbons may be removed, though not necessarily, as a single impression of the types may be made through both ribbons.

Full stroke mechanism

In order to prevent the operator from making only a partial forward and backward stroke of the rocking frames 15 and 29, and thereby prevent erroneous registration, the following mechanism is provided:—

319 (Figs. 2, 7, 9 and 14) represents two detent pawls which are arranged over the rocking frames 15 and 29, respectively, and pivoted on a transverse rod 320. Each of these pawls is provided on its underside with two downwardly diverging detents 321 which are arranged substantially at right angles to each other and on its upper side with a V-shaped ridge 322. Upon turning the detent pawl in one direction, its front detent engages with the upper concentric edge or face of the adjacent rocking frame, while upon turning the pawl in the opposite direction its rear detent engages with said edge. Each of the detent pawls is yieldingly held with either of its detents in engagement with the respective rocking frame by a presser arm 323 pivoted loosely on the transverse shaft 9 and provided at its rear end with a roller or projection which is held in engagement with the ridge of the adjacent pawl by a spring 324 connected with the arm 323 and bearing 130

against the under side of the rod 320, Figures 2 and 14.

The concentric face or edge of each rocking frame is provided with a segmental series of notches 325 and under-cut inclines, 326 converging upwardly from the outer sides of the front and rear notches in the said concentric edge, as represented in Figures 2, 7 and 9. In the rearmost positions of the rocking frames 15 and 29, the front detents of the 10 detent pawls engage with the front inclines 326 of the rocking frames and turn the pawls so that their front detents are depressed into engagement with the foremost notches of the frames, while their rear detents are raised, as 15 shown in Figure 2. The pawls are yieldingly held in this position during the forward movement of the frames by the presser arms 322 bearing against the inclined rear sides of 20 the ridges on the pawls.

As the rocking frames move forward the front detents of the detent pawls engage with one pair of notches after another of the frames 15, 29, and at the end of the forward 25 movement of the frames the rear inclines 326 thereof engage with the rear detents of the pawls and turn the same so that the front detents are raised and the rear detents are depressed into engagement with the rearmost 30 notches 325 of the rocking frames. When the pawls are thus reversed by the rear inclines of the rocking frames, the ridge of each pawl is moved with its highest part in rear of the roller of the presser arm, which causes this 35 arm to now hold the pawl in this position during the subsequent backward movement of its frame.

As the rocking frames move backwardly, the rear detents of the detent pawls engage 40 successively with the notches of the rocking frames and when the latter reach the end of their backward movement, the front inclines 326 thereof engage with the front detents of the detent pawls and depress the same into 45 engagement with the foremost notches of the frames and lift their rear detents into an inoperative position, as shown in Figure 2.

If the operator has moved the rocking frames forwardly more or less, so that one of the intermediate notches in each frame 50 stands in front of its detent pawl and then attempts to move the rocking frames backwardly, before completing the forward movement of the frames, the front jaws of the pawls will 55 engage with the intermediate notches immediately in front of the detent pawls and hold the frames against backward movement. After the rocking frames have completed their forward movement and the pawls have 60 been reversed, each rocking frame is in like manner held against forward movement after the same has been moved backward sufficiently to carry one of its intermediate notches in rear of the rear jaw of its detent pawl. By 65 this means the operator is compelled to com-

plete the stroke of the rocking frames in one direction before reversing the movement of the frames, thereby avoiding displacement of the recording mechanism.

Keyboard mechanism

70

The keys which have been depressed in the operation of recording a number, word or other character are automatically locked in a depressed position until the recording operation of the particular number, word or other character has been completed, and then the depressed keys are automatically released and permitted to be raised by their springs. As shown in Figures 2, 7, 9 and 20-23, 75 the keys are held in a depressed position by a number of locking plates 327, one of which is arranged lengthwise on the left side of the stems of each row of keys. Each of the locking plates is pivoted at its lower end to 80 the top of the keyboard bottom, so as to swing transversely and is provided along its upper edge with a number of downwardly facing catches or shoulders 328 which are adapted to engage with upwardly facing 85 locking shoulders 329 on the stems of the keys. Each of the keys is provided with a convex face below its locking shoulder, consisting of a lower rising portion 330 which inclines upwardly and laterally from the 90 lower part of the key toward the adjacent locking plate, and an upper receding portion 331 which inclines from the upper end of the rising portion to the outer end of the locking shoulder 329 of the stem, as shown in Figures 95 21 and 22. Each locking plate is drawn yieldingly with its catches against the stems of the adjacent rows of keys by a spring 332, as shown in Figure 22. The locking catches of the locking plates bear against the key 100 stems below the convex faces thereof when the keys are in an elevated position as shown in Figure 20.

Upon depressing a key the convex face on its stem deflects the locking plate and when 105 the key has been depressed fully the respective locking catch of the locking plate engages with the locking shoulder 329 of the stem of the depressed key, thereby retaining the parts which are operated by said key in 110 a shifted position.

If a wrong key has been depressed and the operator subsequently depresses the right key the latter during the first part of its downward movement engages the lower or 115 rising part 330 of its convex face with the adjacent locking catch of the locking plate and disengages the respective locking catch from the locking shoulder of the previously 120 depressed key, thereby releasing the same. Upon continuing the depression of the second or correct key after the first or wrong key has been released, the receding or upper part 125 331 of the convex face of the correct key engages with the adjacent locking catch of the 130

locking plate, thereby permitting the latter to approach the key stem and when the correct key has been fully depressed its locking shoulder is carried below the locking catch of the plate and is engaged thereby, whereby the correct key is locked in a depressed position, as represented in Figure 23. By this means any incorrectly depressed key is automatically released by the depression of the correct key and the latter is in turn automatically locked in a depressed position.

Automatic key release

333 (Figs. 20, 21 and 24) represents a transversely movable releasing bar, whereby the keys of the main number-registering devices are released. This bar is arranged transversely in rear of the rear ends of the locking plates of the main number keys and is guided with its ends in the frame of the machine. This bar is provided with a number of upwardly projecting releasing lugs or shoulders 334, one of which is adapted to engage with the right side of a pin or projection 335 on the rear end of each locking plate 327 of the main registering keys, as represented in Figures 7 and 20. Upon shifting the releasing bar 333 toward the left its releasing lugs move the main locking plates in the same direction, thereby releasing any number keys which are held in a depressed position by the same. The main releasing bar 333 when free is shifted toward the right into its retracted position by the resilience of the springs which hold the main locking plates in their operative position.

The releasing bar 333 is shifted into its operative position by a releasing elbow lever 336 which turns on a pivot pin 337 and is connected by its upwardly projecting arm with the releasing bar 333 while its lower arm projects horizontally outward. 338 (Figs. 9, 20, and 21) represents a releasing arm which is arranged lengthwise in the machine and transversely over the lower arm of the releasing elbow lever 336 and which is pivoted at its front end on a pin 339. 340 (Fig 9) represents a longitudinal releasing lever connected by an upright cord 341 with the rear end of the releasing arm 338 and projecting with its rear end into the path of the cross bar 25.

The main number keys are held in their depressed position until the rocking frames 15 and 29 have been moved forward sufficiently to operate the recording mechanisms in accordance with the numbers of the depressed main keys and then the cross bar 25, during the last part of its forward movement with the rocking frames 15 and 29, engages with the releasing lever 340 and depresses the same. The releasing arm 338, during its downward movement with the releasing lever 340, engages with the lower arm of the elbow lever 336 and turns the latter so that its upper

arm moves the main releasing bar 333 toward the left and moves the main locking plates out of engagement with the main number keys, thereby releasing the depressed main keys and permitting them to rise preparatory to setting the machine for recording the next number.

The row of word keys 216 is arranged on the left-hand side of the main keys and the keys 401 of the auxiliary mechanism are arranged on the left hand side of the word keys. Each row of word and auxiliary number keys is provided with a locking mechanism similar to those of the rows of main keys.

The several shifting keys are arranged in a longitudinal row or column on the left side of the auxiliary keys, and the elbow levers operated thereby are arranged one behind the other, as represented in Figure 9.

342 (Figs. 20, 21 and 24) represents an auxiliary releasing bar whereby the locking plates of the auxiliary keys are released. This bar is arranged transversely of the machine, in front of and parallel with the main releasing bar 333 and is adjustably connected therewith, so that the auxiliary releasing bar can be moved into an operative or inoperative position on the main releasing bar.

As shown in Figure 20, the auxiliary releasing bar is pivoted at its inner end to the main key-releasing bar by a horizontal pivot, and its outer end projects through an opening 343 in the frame, as shown in Figure 24, which permits this bar to be manipulated by the operator from the outside of the frame. The auxiliary releasing bar is held in its raised or lowered position by means of two notches or recesses 344, 345, formed one above the other in this bar and each of which is adapted to be engaged with a pin or projection 346 on the main releasing bar, as shown in Figures 20 and 24, by the resilience of the auxiliary releasing bar which is sufficiently elastic for this purpose.

Upon raising the auxiliary releasing bar and engaging its lower recess with the pin 346, the releasing lugs 347 of this bar are carried up to the level of and on the right side of the pins on the rear ends of the locking plates of the auxiliary keys, so that upon moving the main releasing bar toward the left for releasing the main keys, the auxiliary releasing bar is simultaneously moved in the same direction and disengages the locking plates from the auxiliary keys.

Auxiliary key repeat

When it is desired to record the same number at each of a plurality of operations of said auxiliary mechanism, the auxiliary releasing bar is depressed so that its lugs 347 are below the level of the pins of the locking plates of the auxiliary releasing plates, this

bar being held in this position by engaging its upper recess 344 with the pin 346.

Upon now depressing the auxiliary key or keys of the desired number and then operating the machine, the number will be recorded but the key or keys will not be released. While the depressed keys are thus held in depressed position, the recording mechanism can be repeatedly operated, during each of which operations the number represented by the depressed keys is recorded over and over again.

The two columns or rows of word and shifting keys are each provided with a locking mechanism similar to those of the main and auxiliary number keys, but the locking plates of these keys are disengaged from the key-stems by a separate releasing mechanism so as to permit the main and auxiliary number keys to be released without releasing the word and shifting keys.

As shown in Figures 20 and 21, the release of the word and shifting keys is effected by a supplemental releasing bar 348 having lugs 349 which engage with the pins 335 on the rear end of the locking plates of the word and shifting keys and which is guided at its outer end in the main frame. The supplemental releasing bar is pivoted to the upper arm of a releasing elbow lever 350. This lever is pivoted on the pin 337 and its lower arm projects toward the right and underneath the releasing arm 338 adjacent to the rear side of the lower arm of the releasing elbow lever 336.

When both lower arms of the releasing elbow levers 336 and 350 are arranged underneath the releasing arm 338, the depression of the latter by the rocking frames causes the supplemental releasing bar to be moved toward the left so that its lugs disengage the locking plates of the word and shifting keys from their respective stems at the same time that the main and auxiliary releasing bars disengage the locking plates of the main and auxiliary number keys from their respective stems, thereby releasing all of the keys simultaneously after the recording of the words and numbers has been effected.

Repeat key

For the purpose of permitting all the words and numbers represented by the depressed keys to be recorded repeatedly, the releasing elbow levers 336, 350 are shifted toward the right and their lower arms are moved from underneath the releasing arm 338 so that the depression of the lever 340 by the rocking frames will not affect the releasing elbow levers 336, 350 thereby retaining the keys in their shifted position and permitting of producing repeated impressions of the types which correspond to the depressed keys. The releasing elbow levers 336, 350 are moved into

operative and inoperative positions by means of a supporting elbow lever 351, as shown in Figures 9, 20 and 21. This lever is pivoted on a stationary bracket 352 and its upper arm carries the pin 337 on which the releasing elbow levers 336, 350 are pivoted. 353 represents an actuating rock lever which engages with its rear arm against the underside of the lower arm of the supporting elbow lever 351.

354 (Figs. 9 and 23) represents a repeating shifting key having a depending stem which is guided in the top and bottom of the key-board and which engages with its lower end against the front arm of the actuating rock lever 353. Upon depressing the repeating key, the supporting elbow lever 351 is turned by the actuating lever in the direction for moving the releasing elbow levers 336, 350, so that their lower arms clear the releasing arm 338 and will not be affected by the depression of the latter.

Upon releasing the repeating key the supporting elbow lever 353 is returned to its normal position by a spring 355, shown in Figures 9 and 20, and the releasing elbow levers 336, 350 are shifted into an operative position with their lower arms projecting underneath the releasing arm 338. The releasing elbow lever 350 is turned in the direction for moving the supplemental releasing bar 348 into its retracted position by a spring 356 which is secured to the supporting elbow lever 351. The movement of the elbow lever 350 in this direction is limited by a stop 357 on the supporting elbow lever 351, as shown in Figures 20 and 21.

Special key lock

For the purpose of locking the non-printing key 176 or repeating key 354 in a depressed position when it is desired to continue the use of these keys and the mechanism controlled thereby, each of these keys is provided with a movable locking block 362 (Figs. 9 and 23). Each of these blocks is arranged below the top of the keyboard, adjacent to its respective shifting key, and is provided with a thumb piece 363 which is guided in a slot 364 in the top of the keyboard and projects above the same. Upon retracting the locking block from above the stop shoulder of the shifting key, as shown in Figure 22, the key can rise to its uppermost position. Upon depressing this key and then shifting the locking block so that it is arranged between the stop shoulder 44 of the key and the top of the keyboard, as shown in Figure 23 the key is held in a depressed position.

Keys of different aspect

In order to enable the operator to distinguish the figures or numbers readily on the keyboard and thereby enable same to be manipulated more rapidly, the columns of

main figure or number keys are arranged in groups and each group is distinguished by color or otherwise from the adjacent groups.

As shown in Figure 1, the keys in the first three columns, representing figures to the right of the decimal point or less than a whole number, are indicated in black on a white background; the second three columns of figures from the left of the decimal point to the first pointing off place, representing the whole numbers less than thousands, are indicated in white on a black background, and the third three columns of figures from the first pointing off place to the second pointing off place representing the whole numbers between hundreds and millions, are indicated in black on a white background. The words and characters on the word-keys and shifting-keys are also indicated in white on a black background, to distinguish them readily from the intermediate auxiliary number keys which are indicated in black on a white background.

Operation

Assuming that the item "Dec. 14, 1899, 28 rebate 34061.97 5/8" is to be recorded on a bill, the operation, briefly stated is as follows:—

The operator first adjusts the date-printing segments into the proper position by means of the catches 250 and then depresses the dating key 257. All the other shifting keys are released and permitted to rise, whereby all of the devices controlled by these keys are thrown out of gear excepting the recording mechanism which is thrown into gear by the rising of its shifting key 176.

The keys 2 and 8 in the tens and units columns of the auxiliary keys are depressed. The word-key representing "Rebate" in the column of word-keys is next depressed and then the main keys representing the numbers 34061.97 and the fraction 5/8 are depressed in their proper columns. The depression of these keys causes the key levers to be shifted so as to move the proper differential stops into the path of the controlling arms, and the detector dials 238 are turned so as to indicate the numbers or characters of the keys which have been depressed, thereby enabling the operator to correct any error, if a wrong key has been depressed, before recording the item.

If the item appears correctly on the detector dials the operator moves the handle 21 forwardly and backwardly once. During the first part of the forward movement of the handle, the main gear segments are moved forward. During the next part of the forward movement of the handle the main gear segments which correspond with the depressed keys are moved downward a distance corresponding with the numbers or characters of the depressed keys, at which point the key levers arrest the main gear segments through

the medium of the controlling arms. While the main gear segments are effecting their movement, the hammers of the recording mechanism are retracted as represented in Figure 7. After the gear segments have completed their downward movement the hammers are released and produce an impression of the types at the printing line. During the last part of the forward movement of the handle 21, the main gear segments are retracted and are elevated, while so retracted, to their initial position during the subsequent backward movement of the handle. During the last portion of the forward movement of the operating handle the depressed keys have been released preparatory to being again depressed for recording another item.

The recording of further items of this bill is repeated in the same manner. If all the items have the same date, the dating key 257 may be released after recording the first item, whereby the date will be only printed once at the head of the items. If the items bear different dates the dating segments must be adjusted accordingly.

If it is desired to record the main numbers in duplicate the operator shifts the bar 191, Figure 19, so as to permit the duplicate hammer pawls to cause their hammers to actuate the duplicate printing types and thereby produce a separate record, at the printing line of the numbers recorded by the main printing types.

The vertical ruling between the dollars and cents numbers is effected automatically, and if a cross rule is desired at the foot of a column of numbers, the operator depresses the cross ruling key 198.

When it is desired to print the same item or numbers two or more times in succession, the depression of the repeating key 354 shifts the mechanism to produce this result.

By depressing the non-printing key 176 the recording mechanism is thrown out of gear and no record is produced of the numbers.

If it is desired to throw the auxiliary printing mechanism out of action and still permit the main recording mechanism to operate, the thumb piece 234 is moved rearward.

While I have shown what I deem to be the most desirable construction, it will be understood that I do not wish to be limited thereto in my claims, as obviously many of the features of the invention can be greatly varied without departing from the spirit of the invention.

I claim as my invention—

1. The combination of a plurality of variously positionable types, a differential stop member movable independently of said stops for controlling the positioning of said types, and a plurality of keys for controlling positioning of said member.

2. The combination of a plurality of types, a differential stop member movable independ-

ent of said types and comprising a plurality of stops, and a plurality of keys, each of said keys being operable to control movement of said stop member to position a respective one of said stops for controlling a respective one of said types.

3. The combination of a carrier, a plurality of types carried by said carrier, means for moving said carrier to bring any of said types to printing position, a differential stop member movable independently of said carrier for controlling the movements of said carrier to position each of said types, and a plurality of keys for controlling said differential stop member.

4. The combination of a printing device, actuating means therefor, a plurality of keys movable from normal to operative position without effecting movement of any other key which is in normal position, and a member comprising a plurality of stops for differentially controlling said printing device, and operable by each of said keys to render a respective one of said stops operative.

5. A machine comprising a member mounted for forward and backward movement in an arc, a stop device having a series of stops arranged substantially in an arc and being mounted to move in the path of the said member and carry each of its stops in a different arc crosswise of the arc in which said member moves for stopping the latter with any one of said series of stops, and a plurality of keys each corresponding with a respective one of said stops for controlling movements of the same into co-operative relation with said member.

6. In a machine, the combination of a platen for supporting and backing record material, duplicate sets of numeral types co-operative with said platen for printing items in duplicate on said record material, and dating types co-operative with said platen for printing on said record material dates correlated with the items printed by said numeral printing types.

7. A machine comprising, means for carrying a record sheet, an operating member, types a plurality of which may be impressed by a single operation of said operating member so as to effect printing of items on said record sheet, manipulative selecting mechanism for selecting which types of said types shall print, means for printing a vertical rule line in relation to said items, and means for effecting the printing of a horizontal rule line in relation to said items.

8. In a printing mechanism, the combination of a supporting frame, a platen supported by said frame and adapted to back a record sheet, printing types operable to print on a record sheet when backed by said platen, manipulative controlling elements for controlling without effecting printing impression of said types, line spacing mechanism co-operative with said platen so as to shift

said record sheet from one to another print-receiving position relative to said types, and a manipulative operation-controlling member operable to effect printing impressions of said types and to effect operation of said line-spacing mechanism, all of said mechanism being so constructed and arranged that the printing done during each printing operation is visible to the operator at the end of such operation while said operator is in the ordinary position for operating said machine.

9. The combination with a platen and a number of segments each of which is provided with a number of type-carriers, of hammers adapted to engage said carriers, pawls adapted to engage said hammers, shifting elements controllable by said segments and connected with said pawls, and a finger arranged on each higher one of said shifting elements and bearing against the next lower one of said shifting elements.

10. In a printing machine, the combination of a main frame, a platen located so as to be visible above said frame and adapted to back a record-sheet, a plurality of type-carrying members each having an upwardly extending portion carrying the types and a pivoted supporting portion extending from the lower part of the type-carrying portion, an inking ribbon, paper feeding mechanism for causing said platen to line-space said record-sheet upwardly, and operating mechanism operable at a single operation to effect printing on said platen by a plurality of the types carried by said type-carrying members and the feeding of said record-sheet, whereby at the end of each printing operation the item printed during such operation is in view of the operator while said operator is in the ordinary position for operating said machine.

11. In a printing mechanism, the combination of a platen for backing a record-sheet, type, and a device for controlling positioning of said type in printing relation with said record-sheet and platen, the combination of a driver for driving said type to print on said record-sheet, a spring attached to said driver and operable for effecting type-driving movement thereof, and a member operable for retracting said driver and thereby tensioning said spring and operable for releasing said driver to drive said type under impulse of said spring.

12. In a recording mechanism, having a platen, a type, and a carrier for positioning said type, in combination a driver for forcing said type to contact with said platen, a member for retracting said driver, means normally holding said member in ineffective position, and means whereby the positioning of said type by said carrier moves said member into effective position.

13. In a printing mechanism, the combination of a platen for backing a record-sheet,

type, means for controlling the positioning of said type in printing relation to said record-sheet and platen, a hammer provided with a shoulder and operable to drive said type for effecting printing thereby upon said record-sheet, a spring attached to said hammer and operable for driving the same, a detent adapted to engage said shoulder and detain said hammer against the tension of said spring, and operating mechanism for said machine, said detent being automatically disengagable from said shoulder during an operation of said operating mechanism.

14. In a printing mechanism; the combination with type carriers; type movable on said type carriers; means for controlling differential movement of said type carriers to position desired ones of said type for printing; propelling devices for said type; springs, one end of each being secured to a respective one of said propelling devices and the other end to a stationary part of the machine; and means for moving the propelling devices of such of the type carriers as are moved to position respective type for printing so as to tension respective springs and for releasing said propelling devices to permit them to cause printing impression of selected ones of said types.

15. In a printing mechanism the combination with a type carrier, of means for controlling differential movement of said type carrier, type movably supported by said type carrier, a propelling device, a spring, and means whereby movement of said type carrier controls tensioning of said spring for driving said propelling device against said type.

16. In an accounting machine, the combination with type-carriers and means for differentially positioning any of the same, type hammers, springs connecting the hammers with a fixed part of the machine, means for moving the hammers of such of the type-carriers as are moved to printing position so that the spring of the respective hammers will be tensioned, and means for then releasing the hammers.

17. In an accounting machine, the combination with a type-carrier, of means for differentially setting the type-carrier, a type hammer, a spring for actuating the type hammer, and means whereby movement of the type-carrier controls tensioning of the spring.

18. The combination with a printing device; of shouldered positioning devices therefor; a respective series of stops in the path of movement of a shoulder of each of said positioning devices; a plurality of keys, each of which keys may be moved from normal to operative position to position one of said stops without effecting movement of any other key which may be in normal position; and a stop element for each of said positioning devices for holding said devices against movement from normal position.

19. In a printing mechanism, the combination with operating mechanism, of three sets of types operable thereby for printing, the types of each of said sets being movable independently of the types of every other of said sets of types, and the operation of a first of said sets for effecting printing by any of its types automatically effecting operation of a second of said sets of types to effect printing, which second set is intermediate said first set of types and the third set of types, and the operation of said second set of types for effecting printing being incapable of effecting operation of said third set of types to effect printing.

20. In a printing mechanism, the combination of three sets of types, keys for controlling the matter printed by said sets of types, and operating mechanism for operating said sets of types to print according to the control of said keys, the types of each of said sets being movable independently of the types of every other of said sets of types, and the operation of a first of said sets for effecting printing by any of its types automatically effecting operation of a second of said sets of types to effect printing, which second set is intermediate said first set of types and the third set of types, and the operation of said second set of types for effecting printing being incapable of effecting operation of said third set of types to effect printing.

21. In a printing mechanism, the combination of three sets of types operable for printing related matter, the types of each set being movable independently of the types of every other of said sets; three sets of keys, one set of keys for each of said sets of types for controlling printing thereby; and operating mechanism for operating all of said sets of types according to the control of their respective sets of keys, the operation of a first of said sets for effecting printing by any of its types automatically effecting operation of a second of said sets of types to effect printing, which second set is intermediate said first set of types and the third set of types, and the operation of said second set of types for effecting printing being incapable of effecting operation of said third set of types to effect printing.

22. The combination of a main numeral printing device comprising a plurality of sets of individually movable numeral printing types arranged in successive denominational orders; hammers individual to the respective sets; a duplicate printing device comprising a plurality of sets of numeral printing types arranged in successive denominational orders corresponding respectively to the denominational orders of the main printing device and operable for printing duplicates of the numerals printed by said main numeral printing device; a word printing device comprising a plurality of individually movable word

type for printing words in conjunction with numerals printed by said main numeral printing device, manipulative members for controlling said main and duplicate numeral printing devices, manipulative members for controlling said word printing device, and a hand-controlled operation-controlling member for effecting operation of all said printing devices under control of said manipulative members.

23. The combination of a word printing device, a date printing device, separate impression members for the respective devices, manipulative means which by a single manipulation may control setting of said word and date printing devices to print any desired words and dates, actuating elements for the respective impression members and normally out of operative relation therewith, means for placing said actuating elements in operative relation with said impression members, and operating means for operating said actuating elements at a single operation of said operating means.

24. In a machine, the combination of a platen for backing a record sheet, numeral types co-operative with said platen for printing items on said record sheet, a plurality of word-printing types co-operative with said platen for printing words on said record sheet in conjunction with the items printed by said numeral types, dating types co-operative with said platen for printing on said record sheet dates correlated with the items printed by said numeral and word-printing types, manipulative means for said word, numeral and dating types, each of which by a single manipulation may control setting of the associated types to print any desired items and words and dates, separate impression means for said numeral, word-printing, and dating types, respectively, and operating mechanism common to said impression means for causing printing from said types according to the control of said manipulative means.

25. A type driving and controlling mechanism comprising the combination of a plurality of pivoted members to be operated; a second plurality of pivoted members, and each operable to operate its respective one of the first said members; springs for normally holding the second said members disconnected from the first said members, the second said members being operable while so disconnected without operating the first said members; and mechanism for selecting which of the second said members shall be connected with and operate their respective ones of the first said members and forcing the selected ones of the second said members into operative connection with the respective ones of the first said members.

26. A calculating machine comprising a series of type sectors, a hammer for each type

sector, a trip lever for each hammer, means normally holding said trip levers in ineffective position, and a cam on each type sector adapted to co-operate with the trip lever of the respective hammer to positively move the trip lever to effective position when the type sector is actuated.

27. A calculating machine comprising a series of type sectors, a hammer for each type sector, a trip lever for each hammer, a cam on each type sector, adapted to co-operate with the trip lever of the respective hammer to set the trip lever in effective position when the type sector is actuated, and a transferring device for the trip levers to transfer the movement imparted to a trip lever by its respective type sector cam to all the trip levers to the right thereof.

28. In an accounting machine, the combination with a differentially movable type carrier, of a hammer for striking the type carrier a printing blow, a frame having an invariable extent of movement at each operation of the machine, means actuated by the movement of the type carrier for connecting the hammer and frame, and a spring for operating the hammer put under tension by the movement of the frame.

29. A printing mechanism having, in combination, a plurality of type-carriers, arranged side by side, an arm adjacent to each carrier, an energy-transmitting member connected to each arm, each of said arms being movable by its respective carrier, a projection on each arm for moving an adjacent arm, and means for imparting energy to said members.

30. A printing mechanism having, in combination, a plurality of type-carriers arranged side by side, a hammer for each carrier, an arm adjacent to each carrier, an energy-transmitting member for each carrier, each of said arms being engaged by its respective carrier, and a projection on each arm for moving an adjacent arm.

31. A printing mechanism comprising, in combination, a rock shaft, a reciprocatory type-bar, a hammer pivoted between its ends and provided with a controlling spring, a pivoted member operatively associated with said rock shaft so as to be movable thereby, a rocker member mounted upon said pivoted member and adapted to operatively engage said hammer whereby in the movement of the pivoted member the hammer will be placed under the tension of its spring, and means adapted in the movements of the rock shaft to actuate said rocker member whereby to release said hammer for operation by its spring.

32. A printing mechanism comprising, in combination, a reciprocatory type-bar, means for driving the type of said bar to print including a striker, a pivoted member, means

movable with said type-bar to establish an operative association between said pivoted member and said striker, spring means for actuating said pivoted member, means for holding said pivoted member against movement by said spring means, and means for releasing said pivoted member to the action of its spring means after the type-bar and its associated member have been moved into printing position.

33. A printing mechanism comprising, in combination, a reciprocatory bar carrying a plurality of types, key-controlled means for positioning said type bar with a selected

type in position to print; means for driving said selected type to print including a pivoted member, spring means for actuating said member, an oscillatory member adapted to operatively engage said pivoted member, a

pivoted part carrying said oscillatory member and operable to place said spring means under tension, a device operable to swing said oscillatory member whereby to release said pivoted member, and means operatively

associated with said pivoted member and controlled by the type bar in its movement to carry a selected type into printing position, adapted to render operative the pivoted member when the latter is released whereby

to effect a printing of the selected type.

34. The combination of a printing device and a positioning device therefor comprising a lug, a normal stop cooperating with said lug for holding said positioning device in

normal position, means for moving said positioning device from normal position, a stop member comprising a plurality of differential stops for controlling the movement of said positioning device by said means thereby

determining the positioning of the printing device, the construction and arrangement being such that the normal stop is moved from

effective position by the movement of any of the said differential stops to effective position, and a plurality of keys any one of which can be moved from a normal to an operative

position for controlling movement of said stop member without effecting movement of any other key which may be in normal position.

35. The combination of a carrier, a plurality of types carried thereby, a plurality of carrier controlling keys each movable from normal to carrier controlling position without effecting movement of any other key which is in normal position, and a differential stop member comprising a plurality of differentially arranged stops which normally

holds said carrier in normal inoperative position and which is controllable by any of said keys to release said carrier and to control its subsequent movement for positioning said types according to the key operated.

36. The combination of a printing device,

means for operating said printing device to effect printing, a differential stop member comprising a plurality of differentially arranged stops for controlling printing, manipulative printing controlling devices each of which may be moved from normal to print controlling position without effecting movement of any other of said devices which may be in normal position for controlling said differential stop member, and an indicator operable by said stop member for indicating which of said manipulative devices has been set and what will be printed by said printing device.

37. In a machine comprising a horizontally movable carriage, means on said carriage for carrying and line spacing a record sheet and means whereby said carriage may be shifted so as to permit printing by types in different columns, in combination, an operating member, a set of numeral types, a set of dating types, a set of word printing types, optionally operable means for rendering each of said sets of types effective, and means for impressing said numeral types, said dating types and said word types on said record sheet at a single operation of said operating member.

38. In a machine comprising a platen for backing a record sheet and a set of types operable to print on said record sheet; in combination, a plurality of sets of ordinary arranged printing types separate from the above mentioned set and adapted for movement into printing relation with said platen, manipulative means for controlling said movement, connections whereby said movement of any one of a plurality of said sets effects printing from another of said sets of lower order, and a common operating member for effecting printing movement of said types.

39. The combination of a rotary platen adapted to back record material and rotatable for line spacing the same, duplicate sets of types and a series of keys each operable independently of the others to control impression of duplicate types of said sets so as to print separate duplicate records on said record material.

40. The combination of a plurality of sets of number types the types of one of said sets being of the same denominations as the types of another of said sets and the types of each set being arranged in ascending denominational order from right to left; means whereby a plurality of types of one set and counterpart types of another of said sets may be selected and their arrangement in position for being impressed controlled; and a hand-controlled operation controlling member a single operation of which effects impression of the arranged types of said sets so as to produce a plurality of separate counterpart records in the same horizontal line.

41. The combination of a rotary platen adapted to back record material and rotatable for line-spacing the same, duplicate sets of type, controlling members each common to and for selecting a respective type of each of a plurality of said sets and an operating member by each operation of which rotation of said platen may be effected and impression of duplicate types of said sets selected by said 10 controlling members may be effected so as to print separate duplicate records on said record material.

42. The combination of a horizontally movable carriage for carrying a record sheet; 15 a plurality of sets of type; means whereby a plurality of the types of one of said sets may be selected and their arrangement in position for being impressed controlled; a hand controlled operation controlling member a single 20 operation of which effects operation of the selected types so as to print on said record sheet a plurality of separate counterpart records; and means for detaining said carriage against horizontal movement and operable to permit said carriage to move horizontally 25 with relation to said types for printing other duplicate columns.

43. In a calculating machine, a recording member, a series of keys, a controlling member movable into a plurality of operative positions for governing the setting of the recording member, and a movable part common to all of the keys of said series and co-operating with said keys and said controlling 35 member, said movable part being movable relatively to the keys and the controlling member into a plurality of operative positions for limiting the movement of the controlling member into a plurality of positions, substantially as and for the purpose specified. 40

44. The combination of a plurality of sets of main printing types, a plurality of sets of auxiliary printing types, impression devices coacting with said types and cooperatively 45 inter-related so that operation of one of said impression devices may cause operation of another of said impression devices, such interrelationship being interrupted between the impression devices coacting with the main 50 printing types and the impression devices coacting with the auxiliary types, and common operating mechanism for said impression devices of said main and auxiliary types.

45. The combination of a plurality of sets 55 of main numeral printing types, a plurality of sets of auxiliary numeral printing types, impression devices coacting with said types and cooperatively inter-related for cipher-printing such interrelationship being interrupted between the impression devices coacting with the main printing types and the impression devices coacting with the auxiliary types, a key mechanism for said main types, a key mechanism for said auxiliary types, 60 and operating mechanism operable at a single 65

operation to operate types of said main and auxiliary types according to the control of their respective key mechanisms.

46. The combination of a printing mechanism adapted to print a plurality of columns 70 of items, printing in each column being unaffected by printing in another of said columns; a plurality of key mechanisms, one for each of said columns for setting up the items to be printed in the respective column; and an operating mechanism operable at a single 75 operation to effect printing of items in a plurality of said columns.

47. The combination of a plurality of sets 80 of main printing types, a plurality of sets of auxiliary printing types; impression devices coacting with said types and cooperatively inter-related so that operation of one of said impression devices may cause operation of another of said impression devices, such inter-relationship being interrupted between the impression devices coacting with the main printing types and the impression devices coacting with the auxiliary types; a plurality 85 of keys each movable from normal to operative position for setting up the matter to be printed by said main printing types; a plurality of keys each movable from normal to operative position for setting up the matter to be printed by said auxiliary types; and operating mechanism operable at a single operation 90 to effect printing by said main and auxiliary types according to the setting of the respective pluralities of keys; and a carriage for supporting a record sheet in printing relation to said types and movable for permitting said types to print in various horizontal positions on said record sheet. 95

48. A machine comprising a set of types 100 operable for printing numbers on a record sheet, manipulative means for controlling the numbers printed by said set of types, an auxiliary set of types operable to print numbers on said record sheet and in connection with the first said numbers and which may be 105 different from the first said numbers, manipulative means for controlling the numbers printed by said auxiliary set of types, and means whereby one of said sets of types can be rendered ineffective to print while the other of said sets remains effective to print. 110

49. In a machine, the combination of a plurality of sets of main numeral printing types each set comprising significant digit types and a zero type, a plurality of sets of auxiliary numeral printing types each set comprising significant digit types and a zero type, key mechanism for controlling said numeral printing types, type pressing means cooperative with said types for effecting printing of items according to the control of said key mechanism, elements whereby the movement to printing position of one of the significant digit types of either of said pluralities of sets of types renders the type 115 120 125 130

- pressing means effective with relation to the moved significant digit type and with relation to the zero types arranged to the right thereof in its plurality of sets of types without rendering said type-pressing means effective with relation to any types to the left of the moved significant digit type, and without affecting the types of the other of said plurality of sets of types, and means rendering one of said pluralities of sets of types ineffective with regard to said type-impressing means without rendering the other of said pluralities of sets of types ineffective with regard to said type-impressing means.
50. A machine comprising means adapted to line space a record sheet, a set of types operable for printing on said record sheet, an auxiliary set of types operable to print numbers on said record sheet and in conjunction with and which may be different from the numbers printed by those of the first said set of types, a hand-controlled operation controlling member for effecting printing by each of said sets of types on said record sheet and for effecting line spacing of said record sheet by the first said means, and means whereby one of said sets of types may be rendered inoperative relative to said operation controlling member while the other remains operable.
51. A machine comprising a set of types operable for printing numbers on a record sheet, manipulative means for controlling the numbers printed by said sets of types, an auxiliary set of types operable to print numbers on said record sheet and in connection with the first said numbers and which may be different from the first said numbers, manipulative means for controlling the numbers printed by said auxiliary set of types, means for acting upon said sets of types to cause printing thereby, and means whereby said means for acting upon said types may be restricted to acting upon one of said sets.
52. In a machine comprising a carriage for supporting a record sheet in printing relation to types and movable for permitting said types to print in various horizontal positions on said record sheet, the combination of a plurality of sets of main printing types; impression devices coacting with said types and cooperatively inter-related so that operation of one of said impression devices may cause operation of another of said impression devices, such inter-relationship being interrupted between the impression devices coacting with the main printing types and the impression devices coacting with the auxiliary types; a plurality of keys each movable from normal to operative position for setting up the matter to be printed by said main printing types; a plurality of keys each movable from normal to operative position for setting up the matter to be printed by said auxiliary types; and operating mechanism operable at a single operation to effect printing by said main and auxiliary types according to the setting of the respective pluralities of keys.
- WILLIAM S. GABELMANN.

CERTIFICATE OF CORRECTION.

Patent No. 1,742,523.

Granted January 7, 1930, to

WILLIAM S. GUBELMANN.

It is hereby certified that error appears in the printed specification of the above numbered patent requiring correction as follows: Page 21, line 125, claim 1, for the word "stops" read "types"; and that the said Letters Patent should be read with this correction therein that the same may conform to the record of the case in the Patent Office.

Signed and sealed this 25th day of March, A. D. 1930.

**M. J. Moore,
Acting Commissioner of Patents.**
